UNITED STATES PATENT OFFICE

2,067,821

JUSTIFIED LINES TYPEWRITER

William Oscar Bell, Highland Park, Ill., assignor
to Robert H. Loomis, Chicago, Ill.

Application May 31, 1932, Serial No. 614,446

42 Claims.

(Cl. 197—20)

This invention relates to a typewriting machine and its principal object is to provide a machine of new and improved construction for producing printed matter, which in composition will have the appearance of matter printed by a printing press, but which will be produced without the casting or setting of type for each character.

More specifically this invention provides mechanism for printing directly from a font of type characters, combined with a spacing mechanism adapted to regulate the space between words so that the lines will exactly fill a predetermined measure, in other words, so that the lines will be justified.

Another feature of this invention is to provide means for printing each character on its own proper body so that each character will occupy a space adapted to its normal size.

In this connection, the invention contemplates the provision of a type plate having type characters thereon of various widths and improved mechanism for selectively positioning the type plate to bring any desired type face into position for printing.

Another object is to provide an improved mechanism for advancing the paper or other impression receiving material in step by step movements of any desired amplitude.

Another object is to provide an improved mechanism for automatically controlling the movement of the impression receiving material according to the normal width of the particular type character to be struck.

Further objects of the invention will be apparent from the detailed description of the embodiment of the invention shown in the drawings. In this connection, the inventor includes as specific objects the various novel constructions and arrangements of the various parts and their combinations with each other for attaining the above mentioned objects and such other objects as will appear from the following specification.

In the drawings:

Fig. 1 is a front elevation of a machine embodying the principles of my invention.

Fig. 2 is a side elevation of the machine looking from the right hand side of Fig. 1.

Fig. 3 is a plan view of the machine with certain parts cut away for purposes of clearness.

Fig. 4 is the development of the type and plate showing the preferred arrangement of type faces thereon.

Fig. 5 is a fragment of a perforated ribbon employed in connection with the operation of the machine.

Fig. 6 is an enlarged vertical section of the mechanism shown in Fig. 1 for positioning selected type characters in printing position and for imparting spacing movements to the carriage of the machine.

Fig. 7 is a detail plan view of the part of the mechanism shown in Fig. 6 for imparting oscillating movements to the type plate; the jaw members of the mechanism being shown in closed position.

Fig. 8 is a plan view of the same mechanism but showing the jaw members in their normal open position.

Fig. 9 is a detail plan view of the mechanism for imparting reciprocating movements to the type plate with the jaw members of said mechanism in their normal open position and showing also the carriage advance arm and a movable stop plate for limiting the movement of said carriage advance arm in accordance with the width of the type character positioned for printing.

Fig. 10 is a plan view of the justifying mechanism.

Fig. 11 is a perspective view of the justifying mechanism with parts thereof broken away to illustrate the intermeshing relation of the gears and sector members.

Fig. 12 is a plan view of the carriage advance arm together with the cam and associated link mechanism for operating said arm; said parts being shown in the positions which they assume when the arm engages the movable stop plate shown in Fig. 9.

Fig. 13 illustrates the same mechanism with the carriage advance arm moved away from said movable stop plate.

Fig. 14 is a section of a roller clutch mechanism taken through line *a—a* of Fig. 15.

Fig. 15 is a vertical section of the clutch mechanism taken through line *b—b* of Fig. 3.

Fig. 16 is a side elevation of the ratchet mechanisms for advancing the paper in the machine.

Fig. 17 is a section taken on line *d—d* of Fig. 16 to illustrate a yieldable detent for holding the paper advance roll against accidental movement.

Fig. 18 is a plan view of the mechanism for feeding the perforated ribbon through the machine.

Fig. 19 is a sectional elevation of the ribbon feeding mechanism.

Fig. 20 is a side elevation of a portion of the ribbon feeding mechanism showing the ribbon advance mechanism.

Fig. 21 is a view in perspective of the contact pin bar and the contact bar of the ribbon feeding mechanism.

Fig. 22 is a chart showing the various combinations of the justifying mechanism.

Fig. 23 is the wiring diagram of the preferred embodiment of the invention.

Fig. 24 is a plan view of a modified form of the carriage advance mechanism.

Fig. 25 is the same view as Fig. 24 showing another adjustment.

Fig. 26 is a section taken on line $x-x$ of Fig. 25.

Fig. 27 is a plan view of a modified form of type positioning mechanism.

Fig. 28 is a side elevation of the mechanism shown in Fig. 27.

Fig. 29 is a fragmentary front elevation taken on line $y-y$ of Fig. 28.

Referring to Figs. 1 and 2, the invention comprises broadly a carriage A on which the paper or other impression material is carried; a type plate B on which the type characters are carried; a hammer arm C for bringing the type characters and the paper into printing engagement; a type plate positioning mechanism D for selectively positioning the type plate to bring any desired type character thereon into printing position; a carriage moving mechanism E for imparting movements of varying amplitudes to the carriage; and associated with the carriage moving mechanism, a character advance stop F and a spacing stop G, the former for gauging the amount of movement of the carriage according to the size of the character to be struck and the latter for adjusting the sizes of the spaces between words to justify the line.

The invention is designed to be operatively controlled by a perforated ribbon H (Fig. 19) similar to the ribbon produced by the monotype composing machine. This ribbon (a fragment of which is illustrated by Fig. 5) is reversely fed into the machine herein shown so that the perforations last made are the first to operate the typewriting mechanism, the typewriting being performed therefore, in a backward or reverse order.

In order to facilitate an understanding of the detailed description of the operating mechanism, a preliminary explanation will be given regarding the preferred arrangement of the type characters or faces on the type plate B. This arrangement of the type characters, as illustrated in Fig. 4, is identical to the mirror arrangement of the matrices in one of the matrix cases in the monotype system. The particular font of type faces is arranged in vertical and horizontal rows of fifteen characters, each horizontal row containing type faces grouped according to their respective widths or unit values, based on multiples of a unit 1/18th of the width of the capital M. With such arrangement of the type faces any desired character can be readily located by referring to the vertical row, and the horizontal row in which the character lies.

The type plate B is arcuate in shape, being the longitudinal fragment of a cylinder and is mounted for both longitudinal and vertical movements. The type plate B is preferably mounted by suitable means so that it may be readily interchanged with a similar type plate having type of a different size, design, etc. The

first mechanism to be hereinafter described will be the actual printing mechanism and then the means for moving the type plate B to selectively position the same so as to bring any desired type character into printing position.

The printing mechanism

Referring to Fig. 2, the outer face of the type plate B is positioned adjacent the movable carriage A, the latter of which is mounted on guide bars 1 and 2. Guide bar 1 is fixed to the frame of the machine at 3 and 4 (Fig. 3) and is engaged by rollers 5 secured to the carriage A. Guide bar 2 is journaled at 6 and 7 to a fixed part of the machine for a purpose hereinafter described. The movable carriage A carries a sheet of paper or other impression receiving material 8, a paper guide plate 9, paper feed rollers 10 and 11, a receiving cylinder 12, and a rack 13. The rack 13 is geared to a clutch mechanism 14 to be hereinafter described. Interposed between the paper 8 and the type plate B is an ink ribbon 15 which travels by known means, such as is employed in the ordinary typewriter, between a pair of spools 16 and 17 (Fig. 3) mounted at 18 to a fixed part of the machine.

The paper 8 is moved into printing engagement with the ribbon 15 and the type plate B by a magnetically operated hammer arm 19, slidably mounted in a U-shaped supporting frame 20 in back of the paper 8, and adapted to be actuated by an armature 21 and a magnet 22. The magnet is fixed to the supporting frame 20 and the armature 21 is pivoted at one end to the frame 20 and at the other end to the hammer 19. A spring 23 interposed between the armature 21 and the frame 20 holds the hammer 19 in its retracted position, said position being determined by a stop 24 on the hammer which abuts against the frame 20. The type plate B is locked in position during the printing contact of the type by a holding pin 25 adapted to fit into indentations 26 on the back face of the type plate behind each type face. The holding pin 25 is slidably supported in the head of a post 27, the latter of which is secured at 28, 29 to a fixed part of the machine. A spring 30 holds the pin 25 against the type plate B. The pin 25 is retracted from its holding position by means of a lever 31 pivoted on the post 27. The upper end of the lever 31 engages the head end of the holding pin. The lower end of the lever 31 engages an actuating rod 33 which is slidably supported in the post 27. The lower end of the rod 33 seats on one end on a lever arm 34 fulcrumed at 35 to a fixed part of the machine. The other end of the lever 34 carries a roller 36 adapted to ride on an actuating cam 37 which is pinned to a continuously driven vertically disposed shaft 38.

Mechanism for oscillating and reciprocating the type plate

The printing of a particular type character, obviously, requires the type plate B to be moved to a predetermined position relative to the hammer 19. The mechanism for accomplishing this result is as follows:

The type plate B is fixed on a sleeve 39 by means of a web 40. The sleeve is splined by a key or feather 41 (Fig. 3) to a shaft 42 so as to permit the sleeve to move longitudinally of the shaft, but not to rotate thereon. The shaft is journaled at 43, 44 to a fixed part of the machine. The said shaft 42 together with the type-plate are oscillated by means of a gear sector 75

45 secured to the shaft 42 and meshing with a gear sector 46 (Fig. 3) on an arm 47 of a bellcrank. The bellcrank 48 is journaled to oscillate about the axis of the continuously driven shaft 38, heretofore referred to. The shaft 38 is mounted at 49 to a fixed part of the machine and parallel to the shaft 42. The arm 50 (Fig. 8) of the bellcrank 48 is provided with a depending contact pin 51 which is engaged by the 5 closing movement, hereinafter described, of a pair of clamp jaws, thereby swinging the bellcrank about its axis and imparting an oscillatory movement of predetermined amplitude to the shaft 27 and to the type plate B.

15 However, before describing the mechanism for predetermining the amplitude of movement of the bellcrank 48 and the proportionate oscillating movement to the type plate B, it will be well to describe the mechanism for imparting 20 an axial or reciprocating movement to the type plate B. Returning, therefore, to the sleeve member 39 (Fig. 3) which, as previously noted, is splined to the shaft 42. The lower portion of said sleeve member is formed with gear teeth 52 25 to provide a circular rack 53 adapted to be driven by a pinion gear 54 to raise or lower the sleeve member 39. The said gear is keyed to a stub shaft 55 which is rotatably mounted in supporting brackets 56 and 57. The opposite end of 30 the stub shaft is provided with a bevel gear 58 which meshes with a rack 59 carried on a bellcrank 60. This bellcrank, like the bellcrank 50, is also journaled on the vertical shaft 38. The arm 61 of bellcrank 60 is provided with a projecting contact pin 62 adapted to be engaged by the 35 closing movement of a pair of jaws whose movements are controlled, as hereinafter described, to determine the amplitude of movement of the arm 60 and thereby control the 40 extent of the reciprocating movement of the sleeve member 39 and the type plate B. The movement of the other arm of bellcrank 60 does not affect the movement of the type plate B, and, therefore, may be disregarded for the 45 moment.

Having thus far determined the arm 50 of the bellcrank 48 for oscillating the type plate B and the arm 61 of bellcrank 60 for reciprocating the type plate B, the mechanism will next be described for predetermining the movement imparted to the arms 50 and 61 to so position the type plate B that a desired type face is in printing position, i. e., opposite the contact end of the hammer arm 19.

55 The positioning stops

This mechanism comprises broadly two sets of stops of fifteen each, one set 63 (Fig. 8) for the oscillating mechanism (bellcrank arm 50) and 60 the other set 64 (Fig. 9) for the reciprocating mechanism (arm 61 of bellcrank 60). The respective stops of set 63 are designated (Fig. 8) by the characters A to N, inclusive, and likewise the respective stops of set 64 are marked (Fig. 65 9) from 1 to 15 inclusive. Each of the stops of the set 63 for the oscillating mechanism represents a particular vertical row of the type plate B, and are so positioned that when the arm 50 of bellcrank 48 is in alignment with the stop 70 representing for example the G row of the type plate B (Fig. 4) the G row of the type plate B is directly opposite the hammer arm 19. In like manner, each of the stops of the set 64 for the reciprocating mechanism represents a particular horizontal row of the type plate B and

are so coordinated with the arm 61 of bellcrank 60 that when the arm 61 is in alignment with a particular stop, the horizontal row of the type plate B represented by said stop will be directly opposite the hammer arm 19. For a purpose, 5 hereinafter explained, stops 63 and 64 are so arranged that the vertical axes of respective stops of each set are an equal distance apart on a 45° arc described from the axis of the drive shaft 38. Set 64 is positioned directly above set 10 65 and on a similar 45° arc. As will now be readily seen, any desired character on the type plate B may be brought into printing position by aligning the arm 50 with the stop of the set 15 63 representing the vertical row in which the desired character is located, and, at the same time, aligning the arm 61 with the stop of the set 64, representing the horizontal line in which the desired character is located on type plate B. The mechanism for actuating the stops 63 and 20 64 and means for bringing the respective arms 50, 61 into alignment with the particular stops actuated will now be described in detail.

25 The stop actuating mechanism

Referring now to Figs. 1 and 8, the stops 63, being the vertical row stops, are slidably supported in holes in a block 65 which is fixed by suitable means to the frame of the machine. Block 65 is of substantially less thickness than 30 the length of the stops 63, so that they will protrude from the upper and lower surfaces thereof. The upper ends of all of the stops, except the stop 63', are normally held retracted within the block 65 by means of coil springs 68. 35 The lower end of each stop is seated on one of a set of fifteen stop levers 66 (Fig. 3). The stop levers 66 are fulcrumed at 67 to a fixed part of the machine. Each lever is actuated, by a suitable electro-magnet, to move its particular stop 40 upwardly so that it will protrude above the upper surface of the block 65. The stops 63 and their supporting block 65 are mounted slightly below and beyond the outer end of arm 50 which carries the projecting pin 51. 45

The stops 64, being the horizontal row stops, are somewhat similarly supported in a block 69 adjacent the axial or reciprocal positioning arm 61. The stops 64 are slidably supported in the block 69 and, except for the stop 64', are normally held retracted within the block by means of coil spring 73. The said stop 64', however, normally projects below the block 69. Each one of a set of stop levers 71, seated on a corresponding stop 64, is fulcrumed at 72 to a fixed 55 part of the machine and, like the stop levers 66, is actuated, by means of a suitable electro-magnet, to move its particular stop downwardly so that its lower end will protrude from the lower surface of the block 69. The stops 64 and their supporting block 69 are mounted slightly above 60 and beyond the outer end of arm 61, carrying the projecting pin 62.

Before proceeding with the description of the mechanism for actuating the stop levers 66 and 65 the stop levers 71 to move any desired stop out of its normal position, reference will first be made to the operating ribbon H.

When a character key is struck on the monotype composing machine, two perforations are 70 ordinarily made on the monotype ribbon; one perforation denoting the horizontal or numbered row of the type-plate B (Fig. 4) in which the corresponding type face is located; the other perforation denoting the vertical or lettered row 75

(Fig. 4) in which the same type face is located. The said two perforations are required, therefore, to determine the exact position on the type plate B to properly locate a desired type face 5 in position for printing.

As the perforated ribbon is fed into the apparatus it passes between contact members and normally holds open the electric circuit through the magnets for operating the levers 66-71. 10 However, when the two perforations above referred to move into register with predetermined contact members, the said contacts come together so as to close two electric circuits. One of these circuits will energize a magnet adapted 15 to actuate the desired vertical positioning stop lever 66 and the other circuit will energize a magnet adapted to actuate the desired horizontal 20 positioning stop lever 71.

Referring to Fig. 1, each of the magnets 74 is 25 mounted on a suitable bracket 75 which is suitably secured to a fixed part of the machine. Adjacent each of the magnets and projecting somewhat thereabove is a push rod or stop lever 30 actuating rod 76 which extends downwardly and into engagement with one of the stop levers 66, 71, as the case may be. Pivoted to the top of each push rod 76 is a magnet armature 77. Each of the armatures 77 is adapted to respond to the energization of its magnet 74 and to 35 thereby actuate its push rod 76 which will rock its stop lever 71 or 66, as the case may be, to move one of the stops into the path of movement of jaws for operating the levers 50-61.

In the preferred embodiment of the machine 40 the middle or H stop of the group 63 (Fig. 8), designated as 63' and representing the center vertical row on the type plate B, normally protrudes beyond the upper surface of block 65. The lower end of this stop is secured by a suitable socket 78 (Fig. 1) to a stop lever 79 fulcrumed at 67 to a fixed part of the machine. A spring 80 (Fig. 6) tends to hold the stop 63' 45 in its normal position. Lever arm 79 is adapted to be swung by push rod 81, armature 82, and magnet 83, all of which are of like construction as push rods 76, armatures 77, and magnets 74.

In similar manner the middle or #8 stop of the group 64 (Fig. 3), designated by the reference character 64' and representing the center horizontal row on the type plate B, normally protrudes beyond the lower surface of block 69. This stop is actuated by a magnet 84, armature 85, push rod 86 and stop lever 87 in like manner as the other stops of set 64 except that the 50 lever arm 87 to which stop 64' is secured by ball socket 70, is fulcrumed between the push rod 86 and the stop 64' to reverse the movement.

This preferred construction makes it unnecessary to perforate the ribbon when it is desired 55 to indicate the center character of the type plate, said construction also makes it practicable to eliminate one of the perforations when the character desired to be printed is in either of the center rows. The magnets actuating these two stops are wired, as hereinafter described, to be energized simultaneously with the energization of any other magnet.

Mechanism for aligning oscillating and reciprocating arms

70 Journaled on the vertical shaft 38 at a point below the bellcrank 48 is a pair of cooperating clamp jaws 88, 89 (Figs. 7 and 8) which jaws as before noted position the lever 50 relative to 75 a particular stop 63. The outer portion of

clamp jaw 88 is bent upwardly into the same horizontal plane as jaw 89 and both jaw members 88 and 89 are adapted, when in closing engagement, to grip the depending pin 51 of arm 50 and also whatever stop of the set 63 may be 5 projecting above the upper surface of the block 65. Jaws 88, 89 are moved to their closed position by springs 90, 91, and are opened by means of a cam 92, a cam lever 93, and equalizing links 94, 95, 96, the opening movement of said jaws 10 being limited by fixed stops 89a. The cam 92 is keyed at 97 to the vertical shaft 38, and is adapted during the rotation of the shaft to actuate cam lever 93 twice for each revolution of the drive shaft. Preferably, a roller 98 is 15 carried by the lever 93 to bear against the edge of the cam. One end of the cam lever 93 is pivoted at 99 to a fixed part of the machine and the other end is pivotally connected to the center of equalizing link 95. The link member 94 20 is pivoted at one end to the jaw member 88 and at the other end to one end of the equalizing link 95. The link member 96 is likewise pivoted to jaw member 89 and to the opposite end of equalizing link 95. This equalizing or compensating mechanism is necessary from the fact that the position of the clamp jaws 88, 89 when in closing engagement is variable depending upon the particular stop which may protrude 25 into the path of the jaws. 30

A like pair of jaws 100, 101 (Fig. 9) adapted to bring the arm 61 into alignment with any desired stop of the group 64, is operated by a cam 102, cam lever 103, and equalizing links 104, 105, 106 and springs 106a and 106b, stops 101a all 35 of which are of the same construction as the corresponding parts of the jaw members 88, 89 and occupy the same relative positions to the arm 61 and the shaft 38. The outer end of a cam lever 103, however, is pivoted to a fixed sector plate 107, the said sector plate being held against movement by reason of a suitable attachment to the machine frame. 40

It will be seen that with the proper timing, to be hereinafter described, during one-half revolution of the drive shaft 38, the stop actuating mechanisms will move one stop of the set 63 into the path of the clamp jaws 88, 89 and one stop of the set 64 into the path of the jaws 100, 101; the jaws 88, 89, and 100, 101 will close on the respective stops, aligning the respective arms 50 and 61, thereby moving the desired character of type plate B into printing position; and the hammer 19 will be actuated to bring the paper 8, the ribbon 15 and the desired type character into printing engagement. 55

Character space advance

The mechanism now to be described operates 60 to move the carriage A, after a character has been printed, a distance corresponding to the normal width of the next character to be printed. Bearing in mind that the perforated ribbon H (Fig. 5) is fed into the machine in reverse 65 order and consequently the printing is done backward, it will be understood that the next letter to be printed is in effect anticipated and therefore the necessary space can be pre-arranged. 70

The mechanism for advancing the carriage a distance corresponding to the width of the particular character to be struck comprises broadly, the carriage advance clutch mechanism 108 (Fig. 15); a clutch operating arm 109; and 75

the adjustable carriage advance stop or rotary stop plate F.

The carriage advance clutch mechanism 108 is operatively connected with the rack 13 of the carriage A, and is preferably constructed as described in detail in the copending United States application, William Oscar Bell, filed March 3, 1932, Serial No. 596,551 "Apparatus for obtaining variable spacing for typewriters and the like." Issued August 20, 1935 as Patent No. 2,011,887. It comprises briefly a driving element 110, a driven element 111, and a cone clutch 112, the latter comprising a male or driving member 113 and a female or driven member 115. The driving element 110, the driven element 111 and the cone clutch driving member 113 are all journaled on a shaft 114, the cone clutch driven member 115 being keyed at 116 to the shaft 114. The driving element 110 is adapted to fit into the central portion of the driven element 111 and is provided on its outer periphery with a series of spring pressed rollers 117 (Fig. 14) adapted to bind against the driven element 111 when the driving element 110 is moved in a counter-clockwise direction with reference to Fig. 14 and to move freely when moved in the opposite direction. Driven element 111 is provided on its periphery with similar spring pressed rollers 118 adapted to bind against the inner surface of a casing 119 to prevent retrograde or clockwise movement, with reference to Fig. 14, and to ride freely when driven in a counter-clockwise direction (Fig. 14) by driving element 110. The upper portion of driven element 111 may be cast integrally with cone clutch driving member 113 or the latter may be fixed thereto by any suitable means. The casing 119 also encloses the cone clutch mechanism and is secured at 120 to a fixed part of the machine. A spring 121 positioned within the casing 119 tends to hold the cone clutch driven member 115 in operative engagement with the cone clutch driving member 113 through a collar 121 provided with bearings 122 which bear against a flange 123 of the cone clutch driven member 115. The upper end of cone clutch driven member 115 is formed with a gear 124 in mesh with the teeth of rack 13 of the carriage A and is adapted to impart movements thereto. The shaft 114 is slidably mounted in brackets 125, 126 secured to a fixed part of the machine and is adapted to be raised by a solenoid actuated arm 127 (Fig. 2) pivoted at 128 to a bracket 129 which is also raised when the arm 127 is actuated by the solenoid 130. Consequently, when the solenoid 130 is energized, the shaft 114 is raised against the action of spring 121 and the cone clutch mechanism 112 is released. When the cone clutch mechanism 112 is thus released the carriage A is returned to its initial operating position by a spring 115a (Fig. 1) secured at 115b to a fixed part of the carriage and at 115c to the carriage A and which is stressed by the movements imparted to the carriage by clutch mechanism 108. Interposed between the arm 127 and the shaft 114 is a bearing 130a to provide for the rotary movement of the shaft 114.

The clutch operating arm 109 extends from the clutch mechanism 108 to a cross bar 109a (Fig. 6) of an H arm or carriage arm 131. Carriage arm 131 is journaled at 132 and 133 on the shaft 38 and is adapted to receive a maximum movement of 45° from the axis of said shaft by means of a cam 134 keyed at 135 to the shaft. Slidably supported through the ends of carriage

arm 131 is a pin 135a adapted to normally project into the horizontal plane of the stop plate F. Clutch operating arm 109 is adapted to impart a maximum movement to the clutch mechanism 108 which will move carriage A .19635 of 5 an inch, which approximates the normal width of a fourteen point capital M, which is referred to in the art as a fourteen point em. The clutch operating arm 109 is so positioned, however, that it will impart movement to the clutch mechanism upon the movement of the carriage arm 131, toward the rotary stop plate F, that is, the cam actuated movement.

The cam 134 is adapted to oscillate the carriage arm 131 twice for each revolution of the shaft 38 and is operatively connected with the arm by a spring controlled compensating mechanism (Figs. 12 and 13) comprising connecting links 137, 138; cam following link 139; and springs 140, 141. One end of connecting link 20 137 is pivoted at 142 to the carriage arm 131. The other end of said link is pivoted at 143 to the connecting link 138, the latter being pivoted at 144 to a fixed part of the machine. Cam following link 139 is also pivoted at 144 and is provided at its center portion with a cam follower 145 and on one end with a projecting lip 146 adapted to engage one edge of link 138. Spring 140 extends between a flange or projecting arm 147 of link 138 and a like arm 148 formed on the link 139 and is adapted to hold the lip 146 in engagement with link 138. A spring 141, interposed between arm 148 of link 139 and a fixed part of the machine, is adapted to hold link 139 so that cam follower 145 is maintained 35 in engagement with the cam 134. Consequently, when the carriage arm 131 engages the stop, such as the rotary stop plate F, before the cam is advanced to its fullest extent, the additional motion will be absorbed by the cam follower 40 link 139 and the springs 140, 141.

Inasmuch as the driving element 110 of the clutch mechanism 108 (Fig. 14) moves freely and without effect in a clockwise direction (Fig. 14) the spring operated or counter-clockwise 45 swing of the carriage arm 131 (Figs. 12 and 13) serves only to bring the clutch operating arm 109 into an initial operating position which may be described as the position of the carriage arm 131 when swung to the maximum extent by the 50 spring 141. Consequently, in the absence of any stop mechanism, the movement imparted to the carriage A on each oscillation of a carriage arm 131 would be constant and unvarying, i. e., .19635 inch. However, as has been hereinabove noted, 55 the characters on the type plate B are of varying widths and consequently the movement of the carriage A should be varied accordingly. As known in the art, the best arrangement of the type characters as to widths for general 60 purposes is an arrangement which provides three rows for the nine unit characters, two rows for the ten unit characters, and one row each for the five, six, seven, eight, eleven, twelve, thirteen, fourteen and eighteen unit characters (Fig. 4). 65 The units upon which the above figures are based each constitute a 1/18th part of an em. Consequently there are, generally speaking, twelve different positions to which the stop plate F must be adjusted.

Pivoted to the outer end of an arm 149 of bellcrank 60 is a gear 150 (Fig. 6) to which is fixed the rotary stop plate F. The said gear and stop plate assembly is supported on arm 149 by means of a double headed bolt 152 and a 75

nut 153. The gear 150 is in mesh with a rack 154 formed on the rack arm 107 (as best seen in Fig. 9), the latter of which, as previously noted, is supported in a fixed position.

- 5 As will be seen, when the arm 61 of bellcrank 60 is in alignment with stop No. 1, (Fig. 9) which represents horizontal row number 1 on the type plate (Fig. 4) or the smallest characters of the font, the stop plate F will limit the movement 10 of the carriage arm 131, thereby imparting to the carriage A the minimum movement allowed by the stop plate F. As the arm 61 is brought into alignment with stop No. 2 (Fig. 9) the stop plate F will be moved accordingly on rack 15 154 increasing the movement of the carriage arm 131 to accommodate a character of the next highest unit value.

In view of the fact that the unit value of the rows represented by the stops of set 64 do not 20 increase in arithmetic progression, it is necessary to compensate for the variations by a series of steps on stop plate F. These steps are computed as follows: Since the varied sizes of the type of any font are divided into eighteen units, as 25 heretofore described, the carriage arm 131 must move $2\frac{1}{2}$ ($45/18$) to advance the carriage one unit. The arm 61, however, when moved from one stop to the next moves 3.214° ($45/14$). When, for example, the arm 61 is moved out of alignment with stop No. 1 (Fig. 9) and into alignment with stop No. 2 (Fig. 9), the rotary stop plate F would advance 3.214° and thereby increase the movement of the carriage arm 131 30 by a corresponding amount. To compensate for the excess movement, the stop plate F is provided with a step 155. The height of the step is $.714^\circ$ or the amount of the excess movement. The width of the step depends on the number 35 of degrees which the stop plate F will rotate between each position. In the embodiment of the invention, herein shown, the axis of the gear 150 is swung through 45° while the stop plate F is rotated $337\frac{1}{2}^\circ$ or through $15\frac{1}{16}$ of its circumference. Consequently, each of the steps 40 will be $22\frac{1}{2}^\circ$ wide. The axis of the stop plate F is, therefore, so positioned that when the arm 61 is in alignment with stop No. 1 (Fig. 9) the side of the stop plate F having a minimum radius (arbitrarily determined) is five units (the 45 minimum character width—Fig. 4) or $12\frac{1}{2}^\circ$ from the carriage arm 131 when the latter is in its initial operating position. When the arm 61 is brought into alignment with stop 2 (Fig. 9) the axis of the stop plate will move 3.214° away 50 from the carriage arm 131, but the stop plate F will rotate so that the edge of the stop plate F now in the path of the carriage arm 131 is stepped up $.714^\circ$ beyond the previous edge, thereby reducing the increased arc of movement 55 available to the carriage arm 131 by $.714^\circ$ for a net increase of 2.5° which represents one unit. Similar compensating steps are provided for each of the other successive movements in which 60 the carriage is to be advanced but one unit. However, when the arm 61 is advanced from stop No. 5 to stop No. 6 (Fig. 9), both of which represent rows having the same unit value, the amplitude of movement of the carriage arm 131 65 is maintained the same by presenting an edge 70 156 of the stop plate F which has been stepped up the entire amount by which the axis of the stop plate F moves or 3.214° . The stop plate F is provided with similar steps for the other positions of the arm 61 ranging from the minimum 75

advance of 5 units to step 156a representing the 18 unit movement.

As will readily be seen, the stop plate F may be interchanged with another stop plate similarly stepped when it is desired to use a different size font on the type plate B. 5

The justifying arms

Secured to the carriage arm 131 by a screw 157 is a magnet 158 which, when energized, is 10 adapted to actuate an armature 159. One end of the armature is pivoted at 160 to the carriage arm 131. The other end is bifurcated for engagement with a collar 161 on the stop pin 135a. When the magnet 158 is energized, armature 159 will pull the stop pin 135a downward and out of the horizontal plane of stop plate F and into the horizontal plane of stop arm 162, hereinafter referred to as the space stop arm. The carriage arm 131 is thereby thrown out of 20 engagement with the rotary stop plate F and while in such position, the carriage A is moved a distance determined by the position of the space stop arm 162.

Before each line is printed, the space stop 25 arm 162, as previously noted, is first adjusted to justify the line. In other words, the size of the spaces necessary to justify the line is determined before the line is printed. This is made possible by virtue of the fact that the 30 perforated ribbon H (Fig. 5) runs backwards, thereby first presenting the perforations (last made on the composing machine) which indicate the requisite size for each space to justify the line. To facilitate an understanding of the 35 justifying mechanism, brief reference will be made at this time to the theory of the justifying operation.

To justify a line, the spaces between the words must be so adjusted that the last character of 40 the line is exactly in a predetermined position. To effect justification, the surplus space remaining after the completion of a line is divided by the total number of spaces and the quotient is added to each space. In the present invention the fifteen stops 63 and the fifteen stops 64 used in positioning the type plate B, as hereinabove described, are also used for positioning the space stop arm 162. The manner in which these keys are combined to impart varying 45 movements will be later described.

The mechanism for positioning the space stop arm 162 comprises broadly an H arm 163 hereinafter referred to as the maximum adjustment arm and an H arm 164 hereinafter referred to 55 as the minimum adjustment arm. The maximum adjustment arm 163 is journaled at 165, 166 on the shaft 38. The minimum adjustment arm 164 is likewise journaled on said shaft at 167 and 168. The maximum adjustment arm 163 carries a magnet 169 and an armature 170 adapted, when the magnet 169 is energized, to engage a stop pin 171 to move the same against a spring 171a and into the path of jaws 88, 89. The spring 171a is fixed to the pin 171 at 171b 60 and abuts against the lower portion of the maximum adjustment arm 163. The minimum adjustment arm 164 likewise carries a magnet 172 and an armature 173 adapted, when the magnet 172 is energized, to engage a stop pin 174 to 65 move the same against the force of a spring 174a and into the path of the closing movement of the jaws 100, 101. The spring 174a is fixed at 174b to the stop pin 174 and abuts against the upper portion of minimum adjustment arm 70 75

164. The upper end of stop pin 169 normally extends into a block 175, the latter of which is secured at 176 to a machine frame. The lower end of stop pin 174 likewise normally extends into the block 175. The holes in the block 175 for receiving the pins 171-174 are best illustrated in Fig. 10. The holes, fifteen in number, are positioned on the circumference of a 45° arc described about the center of the 5 shaft 38 so that the center of each hole is positioned in a vertical plane passing through the axis of shaft 38 and also through the vertical axis of a corresponding stop of each of the sets 63, 64. When the magnets 169 and 172 10 are energized, the stop pins 171 and 174 are withdrawn from the holes in the block 175 thus moving opposite ends of stop pin 171 into the path of jaws 88, 89 and likewise moving the stop pin 174 into the path of jaws 100, 101. 15

20 When the pin 171 is projected into the path of the jaws 88, 89, it is gripped by said jaws and the maximum adjustment arm 163 is thereby swung into alignment with whatever stop of the set 63 may be projecting from the upper 25 surface of block 65. In like manner the minimum adjustment arm 164 is brought into alignment with whatever stop of the set 64 may be projecting beyond the lower surface of block 69. The selective positioning of the stops 63, 64 for 30 determining the spacing, however, is hereinafter described.

The justifying gear mechanism

35 The upper portion of the maximum adjustment arm 163 is extended to form a gear sector 177 (Fig. 11) which is in mesh with a gear 178 pivoted at 179 to the under surface of space stop arm 162 adjacent the outer end thereof. Gear 178 is in mesh with an intermediate gear 180 which is journaled on a screw bolt 181 to a depressed center portion of the space stop arm 162. Fixed to the intermediate gear 180 by suitable means, is an intermediate gear sector 182 in mesh with a third gear 183 which is 40 fixed to minimum adjustment arm 164. The third gear 183 is moved only by the minimum adjustment arm 164 and consequently when the minimum adjustment arm 164 is stationary, the third gear 183 acts as a rack on which the intermediate gear sector will ride, thereby moving 45 the stop lever 162.

When the minimum adjustment arm 164 and its gear 183 is moved and the maximum adjustment arm 163 is stationary, the gear 183 will 50 move the intermediate gear sector 182, the intermediate gear 180 and the gear 178, but the gear sector 177 being fixed, acts as a rack upon which the gear 178 rides and moves the space stop arm 162. The above intermeshing gears and racks 55 are so proportioned as to provide a ratio of fifteen to one between the movements of the adjustment arms 163, 164 and the space stop arm 162. In the actual operation of the machine, however, the movements of the maximum adjustment 60 arm 163 and the minimum adjustment arm 164 are simultaneous so that the total movement imparted to the space stop arm 162 is the algebraic sum of both movements.

In the preferred embodiment of the invention 70 the operation of the justifying mechanism is computed as follows:

For general purposes the maximum space required by any character is the space occupied by a fourteen point em which is .19362 of an 75 inch. Consequently the maximum movement re-

quired of the carriage may be determined as .19362 of an inch. By arbitrarily fixing the size of gear 124 which meshes with rack 13 (Fig. 2) at one-half pitch diameter, which gives a pitch diameter circumference of 1.5708, it will be 5 found that the movement of .19362 (the width of a fourteen point em) will be 44.37°. Therefore, the maximum movement of the carriage arm 131 to move the carriage A the width of a fourteen point em will be 44.37°. However, in 10 the preferred embodiment of the present invention, the maximum movement is taken as 45° which will impart a maximum movement to the carriage of .19635.

It will be seen, therefore, that with two sets 15 of fifteen keys each available for indicating various movements from zero to .19635 there are 224 possible combinations (excluding the zero combination) for so indicating said movements. The minimum movement which may be indicated 20 will be .0008765 of an inch (.19635 divided by 224). By letting the keys of the set 64 represent this minimum movement, the combination of the zero stop (stop 1) of set 63 and the successive 25 stops of set 64 (as illustrated by Fig. 22) will therefore, run from .0008765 to .012264 (14×.0008765) and the next stop (stop 2) of set 63 will represent a carriage movement of .013147 (15×.0008765); which may be taken broadly as .01315.

With the stops 63 representing a movement fifteen times the movement of stops 64, it is necessary that the gear mechanism on space stop arm 162 be adapted to give the previously noted fifteen to one ratio between the movement of the maximum adjustment arm 163 and the minimum 35 adjustment arm 164. With this ratio both adjustment arms are thereby adapted, when they are both moved their maximum distance of 45° to impart a like movement to the space stop arm 162. Since the minimum movement of the stop 40 arm 162 will be .2009° (45 divided by 224) the minimum adjustment arm 164 will move the stop arm 162 for a total of 2.8126° (14×.2009) and the maximum adjustment arm 163 will move the stop arm 162 for a total of 42.189° (15×.2009 45 ×14). Consequently, it will be seen that when the minimum adjustment arm 164 moves from one stop to the next, it will effect a movement of .0008765 to the carriage A and the maximum adjustment arm 163 will impart a movement of 50 .01315 of an inch to the carriage A.

Line space mechanism

The paper or other impression receiving material 8 is moved into position for the next line 55 to be printed by a paper advance mechanism, (Fig. 16), comprising a ratchet wheel 184, a pawl 185, a lever arm 186, solenoid core 187, solenoid winding 188, and a series of stops 189. The solenoid winding 188 is secured at 190 to the 60 machine framing. The outer end of its core 187 is attached at 191 to the lever arm 186, the latter of which has capacity for movement relative to the ratchet wheel. The guide bar 2, on which the lever 186 is loosely mounted, is keyed 65 at 192 to paper feed roll 10. The pivoted pawl is carried on the lever arm 186 and is adapted to engage the teeth of the ratchet 184 to impart counter-clockwise movements thereto, with reference to Fig. 16. A spring 193 interposed between 70 the pawl 185 and the lever 186 holds the pawl in operative engagement with the ratchet teeth. The inner surface of ratchet wheel 184 is provided with a series of indentations 194 (Fig. 17) adapted to receive a holding detent in the form 75

- of a ball 195 which is pressed into the indentations 194 to prevent retrograde movement of the ratchet wheel. The tension of the spring 196 may be varied by adjustment of the screw 197.
- 5 A series of manually adjusted stops 189 are adapted to be projected into the path of lever arm 186 to limit the movement thereof as desired. Return movement is imparted to the lever by means of a spring 199, the distance of such 10 return movement being determined by the particular stop being used as an abutment for the lever.

Ribbon feed and circuit closing mechanism

- 15 The perforated ribbon H (Fig. 5) is fed to the machine by a mechanism shown in Figs. 18, 19, and 20. This mechanism comprises broadly a suitable frame 200; a spool 201 journaled on the frame 200 and containing the ribbon H; guide 20 rolls 202 and 203; resilient contact fingers 204; a mounting 205 for said contact fingers; a contact bar 206; and a ribbon advance mechanism 207.
- The spool 201 rotates about pins 208, 209 which project from either side of the frame 200. Pin 209 is adapted to be moved by detent 210 when inserting or removing the spool 201. The ribbon H, when in operating position, extends over guide roll 202 against the lower surface of contact bar 206 and thence over guide roll 203 and 30 into a basket or other suitable receptacle (not shown). Guide roll 203 is journaled at 211 and 212 in the frame 200 and is provided at an outer edge thereof with sprocket teeth 213 adapted to engage in marginal openings 213a in the ribbon H. Guide roll 202 is supported on the frame 200 at 214 and 215. Contact bar 206 is supported on brackets 216 and 217, the latter of which are fixed to the frame 200 as indicated at 218 and 219. Each end of the contact bar 206 is fixed to 40 one of the brackets 216, 217 by a bushing 200 threaded at one end and a nut 221. Suitable insulating material 222 is interposed between the bushing and nuts 220, 221 and the supporting brackets 216, 217. A guide roll 213a is held by a 45 spring 221b to hold the ribbon H against the roll 203.

The contact fingers 204, being thirty-one in number and connected with various circuits, as hereinafter described, are supported in a bar 223 (Fig. 21) which extends under the contact bar 206 and is fixed to both sides of the frame 200. The bar 223 is made of suitable insulating material and is provided with thirty-one triangular shaped slots 224, each provided with anchor pins 55 225 adapted to receive the lower end of a contact finger 204. Each of the contact fingers 204 extends into the triangular slots 224 and around the anchor pins 225 (as shown in Fig. 19). The upper ends of the fingers bear resiliently against the under surface of the perforated ribbon H at a location beneath the contact bar 206. The upper portion of each contact finger 204 is curved downwardly to present a smooth surface to the ribbon H. The upper surface of ribbon H rides 60 against the bottom of contact bar 206. When an opening in the ribbon moves over a contact finger, the finger comes into contact with the bar 206 to close an electric circuit.

The ribbon guide roll 203 is operated to advance the ribbon in a step by step movement by means of a double-pawl ratchet mechanism (Fig. 20) which comprises broadly a ratchet wheel 226; an actuating pawl 227; a holding pawl 228; lever arm 229 and a solenoid 230. The ratchet wheel 75 226 is keyed at 231 (Fig. 18) to one end of guide

roll 203. Actuating pawl 227 is pivoted at 232 to lever arm 229 and is held against ratchet 226 by means of a spring 233, the latter of which is fixed to anchor pins 234. One end of lever arm 229 is pivoted at 235 to a fixed part of the machine and the other end is connected by a link 236 with solenoid 230. A spring 237 is interposed between a fixed part of the machine and the lever arm 229 is adapted to normally hold lever arm 229 against stop 238. Holding pawl 228 is pivoted at 239 to a fixed part of the machine and is held in engagement with ratchet 226 by spring 240 fixed to pins 241. The means for energizing the solenoid 230 will appear from the description of the wiring diagram.

15

Wiring diagram

The reference character 242 indicates a positive service main carrying 110 volts and numeral 243 indicates a positive relay main carrying six 20 volts. Each of these mains extends through the machine, as hereinafter described, and leaves through a negative service main and negative relay main, indicated at 244.

The 110 volt service main may be divided 25 broadly into five principal circuits:

1. A circuit 245 runs from service main 242 to binding post 250; through binding post 251 to a switch 252; across the contacts of switch 252 to a motor 253 which drives drive shaft 38 (Fig. 6); 30 and thence to negative main 244.

2. The circuit 246 for operating the magnets lettered A to H inclusive, which magnets operate the correspondingly lettered stops for the vertical rows of the type plate (Fig. 4), extends from 35 binding post 251, which is connected to the positive service main 242, through the H magnet; thence through one of the other magnets depending upon which relay is closed, and thence to the negative main 244 by way of a portion of circuit 40 245. It will be here noted that the H magnet is always energized when the circuit through the lettered magnets is closed by any of the relays. This is necessary to retract the stop 63' (Fig. 6) 45 out of the path of jaws 88, 89 whenever it is desired to project one of the stops 63 into the path of said jaws.

3. Circuit 247 extends from positive service main 242 to binding post 250; thence through binding post 254 to binding post 255; thence 50 through the #8 magnet; thence through one of the other magnets depending upon which relay is closed, and thence to negative service main 244. It will here also be noted that the magnet 8 is always energized when the circuit 247 is closed 55 by any of the relays of the numbered magnets. This is necessary to move the stop 64' (Fig. 6) out of the path of the jaws 100, 101 whenever it is desired to project one of the stops 64 into the path of said jaws.

4. Circuit 248, which is the circuit for actuating the hammer 19 (Fig. 2) extends from binding post 255, the relay of which is connected to the positive service main, as hereinabove described, through binding posts 255a, 255b, 256, 60 257, 258, and 259; thence through a contact 260 to a solenoid actuated switch 261; thence to the hammer magnet 262 (which is the same as the magnet 220 of Fig. 2); thence through cam actuated contact 263 to negative main 244 by way 65 of a portion of circuit 245. Cam actuated contact 263 is adapted to be actuated by a cam 264 on the continuously driven shaft 38 to actuate the hammer twice with each revolution of the shaft.

60

70

75

75

5. Circuit 249, which is the circuit for cutting out the action of the hammer 19 extends from binding post 254, the latter of which is connected to the positive service main 242 as hereinabove described, through one of the relays associated with magnets numbered 1, 2, 6, 9, 10, and 15, respectively, thence through contacts 265, associated with relay connected with the A magnet; thence to a binding post 266; thence to hammer cut out magnet 267 adapted to actuate contact 260 to break the circuit 248; and thence to the negative service main by way of a portion of circuit 245.

It will here be noted that the positions of the type plate indicated by the A magnet (the A row, Fig. 4) and any of the aforementioned numbered magnets (1, 2, 6, 9, 10, and 15) (see Fig. 4) are for quads or space characters and consequently the hammer 19 is interrupted.

20. The six volt relay main may be likewise divided broadly into five principal circuits:

1. Circuit 268 may be described as extending from positive relay main 243 to any of the numbered magnets and any of the contact points numbered 1 to 15 respectively, for example contact point 15. From contact point 15 circuit 268 extends to the relay connected with contact point 15; thence in common with a portion of 110 volt circuit 247 to negative relay main 244. The other circuits for the relays connected with the numbered magnets lead from the contact bar to their respective magnets and thence follow the same course to the negative relay main 244.

2. The circuit 269 extends in like manner from the contact bar 273 through one of the lettered contact points, for example contact point 0, through relay 274, and thence in common with a portion of 110 volt circuit 246 to negative relay main 244.

40. 3. Circuit 270 extends from the contact bar 273 to contact point 275, which is the space contact for moving the carriage A between words; thence through space relay 276 and to negative relay main 244.

45. 4. Circuit 271 extends from contact bar 273 to contact point 277, which operates the maximum adjustment arm 163; thence through maximum adjustment relay 278 to negative relay main 244.

5. Circuit 272 extends from contact bar 273 to contact point 279, which operates the minimum adjustment arm 164; thence through minimum adjustment relay 280 to negative relay main 244 by way of a portion of 110 volt circuit 247.

Having thus described the principal circuits 55 of the 110 volt main 242 and the six volt main 242, the next circuits to be traced will be through the various relays.

The space relay magnet 276 operates four contacts 281, 282, 283, 284, closing a like number of 60 circuits as follows:

Contact 281 closes a circuit to energize the magnet 158 to move pin 135a out of the horizontal plane of stop plate F and into the horizontal plane of space stop arm 162 (Fig. 6). This circuit runs from binding post 258, which is connected with main circuit 248 as hereinabove described, through a wire 285 to contact 281; thence by a wire 286 to magnet 158; and thence to negative service main 244 by way of a portion 70 of circuit 247.

Contact 282 is adapted to interrupt the action of the hammer 19. This circuit can be traced from binding post 258, on main circuit 248, by a wire 285 to contact 282; thence by wire 287 to binding 75 post 289, thence by a wire 290 to binding

post 266; thence by a wire 290a to the hammer cut out relay 267; and thence by a wire 291 to the negative service main 244 by way of a portion of main circuit 245.

Contact 283 acts in conjunction with relay 278 5 to cut out the switch 252, as hereinafter described.

Contact 284 acts in conjunction with relay 280 to interrupt the action of the hammer, as hereinafter described.

The maximum adjustment relay 278 operates three contacts 292, 293, 294, each of which is adapted to close circuits as follows:

Contact 292 is adapted to energize magnet 169 (Fig. 6) to move the pin 171 out of the block 15 175 and into the path of jaws 88, 89. This circuit may be traced from contact positions 259 (on main circuit 248 hereinabove described) by a wire 295 to contact 292; thence by a wire 296 to magnet 169; and thence by a wire 297 to the negative service main 244.

Contact 293 is adapted to cut out the action of the hammer 19. This circuit may be traced from binding post 259 in main circuit 248 by wire 295 to contact 293, and thence by a wire 298 to binding post 266, through a portion of wire 290; thence by wire 290a to hammer cut out relay 267; and thence by wire 291 to the negative service main 244 by way of a portion of circuit 245.

Contact 294 acts in conjunction with contacts 283 of relay 276, cutting out the switch 252 to stop the machine. It will be noted that the perforations in the ribbon for controlling the closing of this circuit are the first perforations made by the operator of the composing machine. Consequently, when the copy is finished, the circuits will operate to stop the machine. This circuit may be traced as follows: From binding post 259, on main circuit 248, by a wire 295, through contact 294, thence by a wire 299 to a binding post 300; thence by a wire 301 through contact 283 of relay 276; thence by a wire 302 to switch 252, where it will cut off the switch 252 by suitable means (not shown), thence by a wire 303 to a 40 binding post 304, thence by a wire 305 to the negative service main 244 by way of a portion of circuit 245.

Contact 294 will also act in conjunction with relay 280 as hereinafter described. The minimum adjustment relay 280 closes four contacts 306, 307, 308, and 309.

Contact 306 closes a circuit to energize magnet 172 (Fig. 6) to move the pin 174 out of block 15 175 and into the path of jaws 100, 101. This circuit 55 may be traced from binding post 256, on main circuit 248, as hereinabove described, by a wire 310 through contact 306, thence by a wire 311 to magnet 172; and thence by a wire 312 to the negative service main 244 by way of a portion of 60 circuit 247.

Contact 307 closes a circuit to cut out the action of hammer 19. This circuit may be traced from binding post 256 by wire 310 through contact 307; thence by wire 313 to binding post 289, 65 thence by wire 290 to binding post 266; thence by wire 290a to hammer cut out 267; and thence by wire 291 to the negative service main 244 by way of a portion of circuit 245.

Contact 308 acts in conjunction with contact 70 294 of maximum adjustment relay 278 to energize magnet 130 (Fig. 2) to release the clutch mechanism 108; to energize a magnet 188 (Figs. 3 and 16) to advance the paper 8 (Fig. 2); and also to energize a relay 314 to open the ribbon 75

advance circuit hereinafter described. This circuit may be traced as follows: from binding post 259, on main circuit 248 by wire 295 through contact 294, thence by wire 299 to binding post 300; thence by a wire 315 through contact 308; thence by a wire 316 to a binding post 317. From binding post 317 the circuit will energize three magnets as follows: first by a wire 318 to cone clutch release magnet 130, thence by a wire 319 to the negative service main 244; second, by wire 318 to paper advance magnet 188, and thence by a wire 320 to the negative service main 244; and third, by a wire 321 to ribbon cut out relay 314, and thence by a wire 322 to the negative service main 244.

Contact 309 acts in conjunction with contact 284 of space relay 276 to interrupt the action of the hammer 19 until both the maximum adjustment relay 278 and the minimum adjustment relay 280 are again actuated. This combination provides means whereby the operator of the composing machine when he has made an error can make perforations which will interrupt the operation of the hammer until the justifying keys are again actuated. This circuit may be traced as follows: from binding post 257, on main circuit 248 by a wire 323 through contact 309 by a wire 324 through contact 284 of relay 276; thence by a wire 325 to solenoid 326 which acts to open switch 261; thence by a wire 327 to binding post 304; and thence by wire 305 to negative service main 244 by way of a portion of circuit 245.

The circuit for operating the ribbon advance solenoid 230 (Fig. 20) may be traced as follows: from binding post 255b, on main circuit 248, by a wire 328 through a contact 329; thence by a wire 330 to ribbon advance solenoid 230; thence by a wire 331 through a contact 332 actuated by a cam 333; and thence by a wire 334 to the negative service main 244 by way of a portion of circuit 247.

As above noted, when the maximum adjustment relay 278 and the minimum adjustment relay 280 are energized, contacts 294 and 309 respectively act to energize relay 314 to open contact 329 of the ribbon advance circuit. Since, it is necessary, therefore, to advance the ribbon H (Fig. 19) to further operate the machine a shunt circuit is provided to close the ribbon advance circuit. This circuit is operated by the carriage A when it returns to its initial operating position. This circuit may be traced as follows: from binding post 255a, on main circuit 248, by a wire 335 through contact 336 operated by the carriage A at the end of its return movement; thence by a wire 337 to wire 330 of the ribbon advance circuit. As the carriage moves, of course, the contacts 336 will be broken.

60   *The operation of the machine*

Before the motor switch 252 is closed to start the operation of the machine, the perforated ribbon H (Fig. 18) is positioned on the ribbon feed mechanism (Fig. 19) so that the portions carrying the last perforations are positioned between the contact bar 206 and the contact fingers 204. As previously explained, the last perforations will be the justifying perforations which act through relays to move the adjustment levers 163, 164; interrupt the action of the hammer 19; release the cone clutch mechanism 14; advance the paper 8 and break contact 329 (Fig. 23) to open the ribbon advance circuit. Consequently, when the ribbon H is in

the above position, by closing the switch 252 the carriage A, the paper 8 and the adjustment arms 163, 164 are all automatically brought into initial operating position. It may be desirable to provide the end of the ribbon H with one or more false perforations which will permit the machine to attain its normal operating speed without printing or advancing the paper 8. These false perforations may be either the maximum or minimum adjustment perforations for, as has been above noted, either of these perforations singly will operate relays to perform the operations above noted except that the paper 8 will not be advanced.

However, to facilitate an understanding of the operation of the machine, a typical printing operation will be described before describing the justifying operation.

It will be assumed, for example, that the perforated ribbon H has just advanced to a position in which two perforations are under the contact bar 206 and over the contact fingers 204. It will be further assumed that these perforations represent the character M, which is found on vertical row F and horizontal row 15 of the type plate B (Fig. 4).

For convenience in understanding the timing of the machine, the operations will be set forth in numbered paragraphs, all the operations appearing under the same number being practically simultaneous.

I.—One of the perforations will close the F magnet relay, thereby energizing magnet H and magnet F (see Fig. 23).

The other perforation will close the #15 magnet relay, thereby energizing magnet 8 and magnet 15 (see Fig. 23).

The H magnet (magnet 83) will actuate armatures 82, push rod 81, and stop lever 79 to move stop 63' (H stop) out of its normal position in the path of jaws 88—89. (See Fig. 1).

The F magnet will actuate its armature 77, push rod 76, and stop lever 66 to move F stop of set 63 into the path of the jaws 88—89 (see Figs. 1 and 8).

The #8 magnet (magnet 84) in like manner will move stop 64' (#8 stop) out of the path of jaws 100, 101 and the #15 magnet will move the 15 stop of the set 64 into the path of said jaws (see Figs. 1 and 8).

At the same time cam 37 will rock lever arm 14 to lift holding pin 25 out of engagement with type plate B.

II.—The jaws 88, 89 will close into gripping engagement with the F stop of set 63 embracing contact pin 51, thereby aligning lever arm 50 with said stop. This movement of arm 50 will be transmitted by gear sector 46 to gear sector 45 (see Figs. 7 and 8).

Gear sector 45 rotates shaft 42 and sleeve member 39, the latter being splined to shaft 42, will thereby oscillate type plate B so that row F of type characters will be positioned opposite the end of hammer 19 (see Fig. 2).

The jaws 100, 101 will close into gripping engagement with the 15 stop of set 64 and also embrace the contact pin 61, thereby aligning lever 62 with said stop (see Figs. 3 and 9).

This movement will be transmitted by rack 59 to the bevel gear 58, stub shaft 55, gear 54 and to sleeve member 39, thereby moving type plate B axially until the row 15 of type characters is opposite hammer arm 19 (see Fig. 2).

With this combined movement of type plate 75

B, the desired character (M) will be opposite the end of the hammer 19.

Responsive to the movements of lever arm 61, rotary stop plate F will move on gear sector 154 5 and rotate to present edge 156a to the carriage arm 131 (see Figs. 3 and 9).

III—The carriage arm 131, having been swung into its initial operating position by spring 141, 10 will now be moved by the cam 134 to the rotary stop plate. (See Figs. 12 and 13).

This movement of the carriage arm 131 will be transmitted through clutch operating arm 109 to the driving element 110 of clutch mechanism 108; spring pressed rollers 117 will bind against 15 driven element 111; and driven element 111, acting through cone clutch mechanism 112, will drive the carriage rack 13 and advance the carriage A (see Figs. 2, 14, and 15).

At the same time cam 37 will return lever arm 20 34 to its normal position; rod 33 will thereby move away from lever 31 and spring 30 will move the holding pin 25 into the indentation 26 located back of the M type face, thereby locking the type plate in position (see Fig. 2).

IV—With the carriage thus advanced and the type plate B thus locked in position, the cam 264 25 will close the hammer circuit to energize the hammer magnet 22 and bring the hammer 19 into printing contact with the paper 8, ink ribbon 15 and type face M.

While the hammer 19 is thus printing the desired character, the cams 92, 102 start opening jaws 88, 89 and 100, 101, respectively. (See Fig. 1.)

V—When the printing operation is completed the cam 333 will close the ribbon advance circuit to energize solenoid 230 to actuate arm 229. The arm 229 will rotate guide roll 203 to advance the ribbon H to bring the next perforations over 40 the contact fingers 204. The ratchet mechanism 226 will hold the ribbon in the advanced position (see Figs. 19 and 20).

As the ribbon H thus advances, the jaws 88, 45 89 and 100, 101 are brought into open position by their respective cams 92, 102, and the carriage arm 131 will begin its negative or spring actuated movement.

This completes the cycle of a typical printing operation of the machine. Like operations will 50 continue until a word is typed and a space perforation appears between the contact fingers 204 and the contact bar 206. When such space perforation appears it will operate a relay, as hereinabove noted, to energize magnet 158 to move pin 135a out of the horizontal plane of stop plate F and into the horizontal plane of space stop arm 162 (Fig. 6) and to interrupt the action of hammer 19. The typical cycle of operation above noted, therefore, will remain the same except that the carriage arm 131, instead of being limited in its movement by rotary stop plate F (as above noted in operation III) will be limited by space stop arm 162 which has been previously adjusted by the justifying levers 163, 164, and instead of the hammer 19 being actuated, (as above noted in operation IV) the circuit will be open and no printing engagement will take place.

As soon as a line has been printed four justifying perforations will ordinarily appear to position the space stop for the next line; one each for the maximum and minimum adjustment relays, one for positioning the maximum adjustment arm 163, and one for positioning the minimum adjustment arm 164 (Figs. 6 and 10). It 70 will be assumed, for example, that the operator

of the composing machine computed, or was otherwise informed, that in order to justify the next line the spaces should be .183 of an inch wide. In that event, the two positioning perforations would be as follows:

The perforation for positioning the maximum adjustment arm would actuate stop 14 of group 63 which is the same as stop N of Fig. 8. The number of the stop is computed by dividing the desired space (.183) by the space represented by 10 this group of stops (.01315) and adding one, since the #1 key represents zero.

The perforation for positioning the minimum adjustment arm 164 would actuate stop 15 of group 64 (Fig. 22) which is the same stop 15 of 15 Fig. 9. This is computed by dividing the minimum adjustment represented by this group (.000877) into the remainder left over in computing the stop of group 14, and adding one since the #1 key of this group also represents zero. 20

The operation of the justifying mechanism, therefore, is as follows:

(A) The magnet 112 is energized to move pin 174 into the path of jaws 100, 101, and magnet 169 is energized to move pin 171 into the path 25 of jaws 88, 89 (see Fig. 6).

Stop 14 of group 63 (being stop B of Fig. 8) is moved, as hereinbefore described, into the path of jaws 88, 89 and stop H is moved out of the path of the jaws as hereinbefore described. 30

The stop #15 of group 64 is likewise moved into the path of jaws 100, 101 and the stop 8 is removed from its normal position, as described.

(B) The respective jaws then close on the stop as hereinabove described, embracing the pins 174 and 169 (Fig. 6) thereby aligning the maximum adjustment arm 163 with stop 14 (stop N) of group 63 and also aligning minimum adjustment arm 164 with the stop 15 of group 64.

This movement is transmitted through the gear 40 mechanism on space stop arm 162 (Figs. 10 and 11) as hereinabove described to impart a movement to the space stop arm 162. Referring again to Fig. 22, it will be seen that the space stop arm 162 is now in a position which will 45 limit the movement of the clutch mechanism 108 to .18320 of an inch, in other words, coming within .0002 of an inch from the desired space.

While the justifying mechanism is thus being 50 positioned, the other relays operated by the justifying perforations have cut out the action of the hammer 19, opened the ribbon advance circuit and released the cone clutch mechanism 14.

The cone clutch mechanism 14 is released 55 through the energizing of solenoid 130 which rocks lever arm 127 to move shaft 114. The driven female element 115 of the cone clutch 14 being keyed to shaft 114 is thereby moved out of engagement with driving element 113 and 60 the clutch is released. It will be noted that when the female element 115 is thus moved it moves against the action of spring 121.

When the clutch mechanism 14 is thus released the carriage A is returned to its initial 65 operating position by a spring 115a which has been tensioned by the movements of the carriage in the opposite direction.

As the carriage A reaches its initial operating position it will close contacts 336 (Fig. 23) of the 70 shunt circuit 335, 337 of the ribbon advance circuit. The ribbon advance circuit is, therefore, closed as soon as actuated by cam 333 and the machine then starts on the normal operating cycle first above described.

It should be noted, however, that as soon as the justifying perforations are moved from the contact pins 104, the circuit energizing magnets 169 and 172 are opened and the pins 174 and 171 are drawn into block 175, (Fig. 6). The particular hole in block 175 into which the pins will be drawn depends of course upon the position of adjustment arms 163, 164.

When the end of the ribbon H is reached, the 10 last set of perforations (the first made on the ribbon) actuate the space relay and the maximum adjustment relay, as hereinabove described, to stop the machine.

Modified constructions

5 Figs. 24, 25, and 26 show a modified form of the clutch operating mechanism whereby the movement imparted to the clutch may be varied according to the particular size of the font used 20 on type plate B.

In the embodiment of the invention shown in Figs. 1 to 23, inclusive, when the type plate B is provided with a font having a different set size, it is necessary to insert a different rotary stop 25 plate F which is provided with steps which will vary the movements of carriage arm 131 in accordance with the set size of the new font. This condition is obviated by the modified construction 30 shown in Figs. 24, 25, and 26. This modified construction comprises broadly means for varying the relative movements of the clutch mechanism without requiring any change in the form or size of the rotary stop plate F, shown in Fig. 3.

Referring to the modified construction shown 35 in Figs. 25 and 26, shaft 114a and clutch driving element 110a may be and preferably are the same as the corresponding members 114 and 110, respectively, shown in Fig. 15. Keyed to the lower portion of driving element 110a is a gear 40 sector 338 in mesh with an idler gear 339, the latter of which is adapted to engage a removable driving gear sector 340. The idler gear 339 is pivoted to an arm 341, which may be oscillated about the axis of the shaft 114a. Arm 341 is 45 formed with a handle 342 adapted to removably engage a series of holes 343 in a gauge plate 344 secured to a fixed part of the machine. The driving gear sector 340 is removably secured to a rotating member 345 which is journaled to a 50 pivot pin 346, the latter of which is mounted in a supporting arm 347 which is a fixed part of the machine. Rotating member 345 is provided with a threaded sleeve portion 348 and a centering pin 349 for holding the sector 340 in position. A nut 55 350 in engagement with the threaded sleeve portion 348 holds the gear sector 340 in engagement with the rotating member 345 and the centering pin 349. An angle plate 351 is fixed to the lower portion of rotating member 345 to an adjustable 60 crank arm 352 by means of screws 353 and 354 which extend through slots 355 and 356 on said angle plate 351. The adjustable crank arm 352 is pivoted at 357 to clutch operating arm 109a and is engaged by an adjustment screw 358, the 65 latter of which is fixed to angle plate 351. The adjustable crank arm 352 is slotted at its center portion to permit horizontal adjustment with relation to pivot pin 346 that is, to permit the crank arm 352 to be moved laterally at a right 70 angle to the axis of the pivot pin 346.

The gear sector 340 of Fig. 25 is adapted to transmit the movements of clutch operating arm 109a to the gear sector 338 in the ratio required for a fourteen point set font. If the 75 clutch operating arm 109a is actuated in like

manner as clutch operating arm 109 of Fig. 5, this ratio will be one to one. If, however, the set size of the font on type plate B should be changed, for example, to a six point set, gear sector 340 is replaced by a smaller gear sector 359 (Fig. 24) to vary the ratio for the new font. This change is made by unscrewing the nut 350, removing the gear sector 340, inserting the gear sector 359, and replacing nut 350. The idler gear 339 is brought into mesh with gear sector 359 by moving arm 341, the latter of which will be held in the desired position by a pin in handle 342 which will engage one of the holes 343 in gauge plate 344. Any minor adjustment made necessary by such change of 15 sectors may be made by varying the length of the crank arm 352 by turning the adjustment screw 358.

Referring now to the modified mechanism as shown in Figs. 27, 28, and 29, for reciprocating 20 and oscillating the type plate B. The type plate B is slidably mounted by means of web members 360 and 361 to a vertical shaft 362, and two vertical guide rods 363 and 364. Vertical shaft 362 corresponds to shaft 42 (Fig. 2). 25 Guide rods 363 and 364 are held in fixed relation to the shaft 362 by means of web members 365, 366 so that when the oscillating arm 47 (Fig. 2) is moved, as noted in the first described 30 embodiment of the invention, such movement will be transmitted to the type plate B through the rods 363 and 364.

A yoke 367 formed on web 360 is provided with a clamp 368 adapted to engage a cable 369. The cable 369 extends round a plurality of sheaves 370, 371, 372, and 373. The sheave 370 is mounted on a bracket arm 374 comprising a fixed part of the machine; sheave 373 is pivoted to a stub shaft 375 projecting from a depending arm 376 of a supporting plate 377 fixed to 40 the frame of the machine; and sheaves 371 and 372 are pivoted on arms 378 and 379 respectively which are also depending from supporting plate 377. The cable 369 is attached to an anchor pin 380 on sheave 373 and is also provided with 45 tension spring 381.

A gear 382 which is rigid with the lower face of the sheave 373 is in mesh with a gear sector 383 formed on a bellcrank 60a corresponding to the bellcrank 60 of Fig. 3. Bellcrank 60a is 50 actuated in like manner as bellcrank 60, and these movements are transmitted to the type plate B through gear sector 383 which moves gear 382 and sheave 373 to cable 369, the latter of which being fixed at 368 to the web member 360 of supporting type plate B, will impart 55 the desired reciprocating movements to the type plate.

The oscillating arm 47, which is the same as shown in Fig. 8 is in mesh with a gear sector 60 384 which is formed on web member 366. Consequently, when the oscillating arm 47 is actuated as above described, the movements will be transmitted through gear sector 384, web 366 and guide rods 363 and 364 to the type plate B. 65

The particular machine illustrated and described is merely a typical embodiment of all the features above described and is not to be construed as limiting or narrowing the scope of this invention as, obviously, a great many 70 changes can be made in the construction and in the combination and arrangement of the several parts without departing from the general principles of operation herein disclosed.

Obviously, also, this invention may be op- 75

erated by other means than electricity, such as compressed air, for example. Nor is it intended to restrict this invention to operation by a perforated ribbon as it may well be seen that the machine might be operated manually by a skilled operator, the matter of line justification being previously determined by experiment, mathematical computation, or otherwise.

I claim:

- 10 1. In a typewriting machine, the combination of a type plate member mounted for rotary and axial movements in either direction and having a plurality of type characters thereon, a supporting member positioned adjacent said type plate for holding impression receiving material, mechanism for imparting axial and rotary movements in either direction to said type plate with relation to the impression receiving material, and a plurality of movable stop members adapted to be operated selectively to limit the movement of the type plate to bring any predetermined type character directly into printing position from any previous position.
- 15 2. In a typewriting machine, the combination of a movable type plate member having a plurality of type characters thereon, a carriage member for supporting material adapted to receive impressions from said type characters, mechanism for moving said type plate with relation to the carriage member comprising a lever connected with said type plate member, spring actuated jaw members for releasably engaging said lever to rock the same to various positions, and a plurality of movable stop members adapted to be operated selectively to be engaged by the jaw members to limit the movement of said jaw members to a predetermined position, thereby presenting a previously selected type character in printing position.
- 20 3. In a typewriting machine, the combination of a type plate member having a plurality of type characters thereon, a carriage member for supporting material adapted to receive a series of impressions from said type characters to form words, a driven shaft adjacent said type plate, a lever arm journaled to said shaft and having a gear sector at one end thereof, means intermediate said gear sector and said type plate whereby said gear sector is adapted to impart oscillatory movements to said type plate and means comprising a pair of clamp jaws operated by said driven shaft to engage said lever arm and a plurality of movable stop members cooperating with said clamp jaws for selectively moving said lever arm to oscillate the type plate so that a desired type character is in printing position with relation to the impression receiving material.
- 25 4. In a typewriting machine, the combination of a carriage for supporting impression receiving material, a type plate member journaled adjacent said carriage and having a plurality of type characters thereon, mechanism for imparting oscillatory movements to said type plate member comprising a driven shaft, a lever journaled thereon and provided with a gear sector, a gear sector segment on the type plate member meshing with the first mentioned gear sector, cooperating clamp jaws journaled on said shaft for releasably engaging said lever to move it into any desired position, spring means for moving said jaws toward each other and into said engagement with said lever, means for limiting the movement of said jaws to a predetermined posi-

tion to present a type character in printing position, and means operable by the movement of said shaft for moving said jaws out of engagement with said lever.

5. In a typewriting machine, the combination of a carriage for supporting impression receiving material, a type plate member movably supported adjacent said carriage and provided with a plurality of type characters thereon, means for imparting axial movement to the type plate to bring a desired type character into printing position, said means comprising a toothed rack on the type plate member, a sector lever, gearing operatively connecting said lever and rack, spring actuated jaw members for releasably engaging said sector lever to move it about its pivotal axis and stop means selectively operable for limiting the movement of said jaws to a predetermined position.

10 6. In a typewriting machine, the combination of a carriage for supporting impression receiving material, a type plate member movably supported adjacent said carriage and provided with a plurality of type characters thereon of various widths, means for imparting axial movement to the type plate to bring a desired type character into printing position, comprising a toothed rack on the type plate member, a sector lever, gearing operatively connecting said lever and rack, spring actuated jaw members for releasably engaging said sector lever to move it about its pivotal axis, means for limiting the movement of said lever and jaws to predetermined positions, comprising a series of stop pins movable into the path of movement of said jaws, and means for selectively operating the desired stop pin to limit the angular movement of said jaws in accordance with the type character desired to be positioned for printing.

15 7. In a typewriting machine, the combination of a carriage for supporting impression receiving material, means for imparting step by step movements to said carriage, a type plate member supported adjacent the carriage and having type characters thereon of various widths arranged in rows, means for imparting axial movement to the type plate member to bring a desired row of type characters into printing position, comprising a sleeve fixed to the type plate member and formed with circular rack teeth thereon, a shaft disposed at right angles to said sleeve, a gear at one end of the shaft meshing with said sleeve rack, a bevel gear at the other end of said shaft, a lever sector meshing with said bevel gear, means for swinging said lever sector comprising spring actuated jaws pivoted on the same axis as the lever sector and adapted to releasably engage and move the lever sector to a predetermined position, stop means determining the arcuate movements of said jaws and lever sector, means for imparting rotational movement to the type plate to bring a predetermined type character of said row into printing position, and means selectively operated for controlling the last mentioned movement in accordance with the type characters desired.

20 8. In a typewriting machine, the combination of a carriage for supporting impression-receiving material, an arcuate type plate member supported adjacent said carriage and having type characters thereon of various widths arranged in rows, each row being composed of characters of uniform widths, means for imparting both oscillatory and axial movements to said type plate to bring desired type characters into print-

- ing position and means for imparting to the carriage step by step movements of amplitudes corresponding to the respective widths of the type characters positioned for printing, comprising a driven shaft, a lever movable on the shaft, means connecting said lever with said carriage, a cam on said shaft for operating the lever, and a variable position stop device for limiting the operative movements of said arm.
10. In a typewriting machine, the combination of a carriage for supporting impression-receiving material, an arcuate type plate member supported adjacent said carriage and having type characters thereon of various widths arranged in rows, each row being composed of characters of uniform width, means for imparting both oscillatory and axial movements to said type plate to bring the desired type character into position and means for imparting to the carriage step by step movements of amplitudes corresponding to the respective widths of the type characters positioned for printing, comprising a driven shaft, a lever movable on said shaft, a cam on the shaft, angularly disposed links for transmitting movements of the cam to said lever, means for limiting the operating movements of said lever in accordance with the axial movements of said type plate comprising an arm movable about the axis of said shaft during the axial movement of the type plate, and a stop member rotatably supported on said arm and formed with a plurality of stop surfaces adapted to be engaged by said lever, a fixed gear sector, a pinion on said stop member meshing with the sector whereby movement of said arm a predetermined distance rotates the stop member a distance to present a predetermined stop surface for engagement with said lever.
10. In a typewriting machine, the combination of a type plate member having a plurality of type characters of various widths arranged in fixed vertical and horizontal rows, a carriage member for supporting impression receiving material adapted to receive impressions from said characters, means for selectively positioning said members in relation to each other for successive impressions of type characters of different widths to form a series of words, space controlling mechanism adapted to be set before the printing of said words to determine the width of the spaces to justify the line, said spaces all being of equal amplitude and means comprising spring actuated jaws for automatically moving said space controlling mechanism to its adjusted position.
11. In a typewriting machine, the combination of a type plate member having a plurality of type characters of various widths, a carriage member for supporting impression receiving material adapted to receive impressions from said type characters, means for selectively positioning said members in relation to each other for successive impressions of type characters of different widths to form a series of words, and space controlling mechanism for adjusting the spaces between said words for justifying the lines comprising a stop arm pivoted to oscillate in a predetermined path, a pair of actuating arms pivoted to oscillate about the same axis as the stop arm, and a train of intermeshing gears operatively connecting said actuating arms with the stop arm and with each other to effect a differential relation in the movement of said arms.
12. In a typewriting machine, the combination of a plurality of type characters of various widths, a carriage member for supporting impression receiving material adapted to receive impressions from said type characters, a driven shaft, a stop arm pivoted to oscillate about said shaft in a predetermined path, a gear on the arm, an operating lever having a lever sector meshing with said gear, a small gear rotatably supported on said lever sector in a position to mesh with the large gear, a gear sector fixed to the last named small gear, a second operating lever journaled on said shaft, a pinion fixed thereto pivoted on said shaft and meshing with the last named sector, and means for moving said operating arms to various selected positions to move the stop arm to its adjusted position.
13. In a typewriting machine, the combination of a carriage member for supporting impression receiving material, a type plate member movably supported adjacent said carriage member and having a plurality of type characters thereon, and means for selectively positioning said type plate to bring any desired type character into printing position with relation to the impression receiving material, said means comprising a cable fixed to said type plate member, a plurality of sheaves supporting said cable, a driven shaft, and a lever arm journaled on said shaft and operatively connected with said sheaves.
14. In a typewriting machine, the combination of a carriage member for supporting impression receiving material, and a type plate member movably supported adjacent said carriage member, and provided with a plurality of type characters thereon, means for imparting axial movement to the type plate member to bring a series of desired type characters into printing position, said means comprising a cable fixed to said type plate member, a sheave adapted to move said cable, a driven shaft, a lever arm journaled to said shaft, gearing operatively connecting said lever and sheave, spring actuated jaw members journaled on said shaft for angular movement and adapted to releasably engage said lever arm to move it about its pivotal axis, stop means selectively operable for limiting the movements of said jaws to a predetermined position, and means operable by the movement of said driven shaft for releasing said jaw members from their engagement with said stop means.
15. In a typewriting machine, the combination of a type plate member having a plurality of type characters thereon of varied widths arranged in vertical and horizontal rows, the characters in each horizontal row being of uniform width, a carriage member for supporting impression receiving material adapted to receive a series of impressions from the type plate member to form words, a driven shaft adjacent the type plate, a type plate oscillating lever journaled to said shaft and being operatively connected with the type plate to impart oscillatory movement thereto, a type plate reciprocating lever journaled to said shaft and being operatively connected with the type plate to impart reciprocal movements thereto, a pair of clamp jaws journaled on said shaft and adapted to grip said oscillating lever, a pair of clamp jaws journaled on said shaft and adapted to grip said reciprocating lever, a series of stop members adjacent the oscillating lever, each of which represent a predetermined arcuate

position of the type plate to bring a desired vertical row of the type plate into printing position, a series of stop members adjacent the reciprocating lever, each of which represents a predetermined axial position of the type plate to bring a desired horizontal row of the type plate into printing position, an electro-magnet for operating each of said stop members to move one stop of each series into the path of movement of its adjacent clamp jaws to determine the movement of the oscillating lever and the reciprocating lever to bring a desired character into printing position, means for bringing said character and the impression receiving material into printing engagement, means for moving the carriage member varied distances according to the size of the characters to be printed, spacing means for automatically moving the carriage member between words to justify the line, means for adjusting the spacing means, means for moving the carriage member through successive lines of printing and means for returning the carriage member to its initial operating position.

16. In a typewriting machine, the combination of a type plate having a plurality of type characters thereon of varied widths arranged in vertical and horizontal rows, the characters in each horizontal row being of uniform width, a movable carriage adapted to support impression receiving material, a driven shaft adjacent the type plate, a type plate oscillating lever journaled to said shaft and being operatively connected with the type plate to impart oscillatory movements thereto, a type plate reciprocating lever journaled to said shaft and being operatively connected with the type plate to impart reciprocal movements thereto, means for selectively positioning the type plate oscillating lever to bring a desired vertical row of the type plate into printing position, means for selectively positioning the type plate reciprocating lever to bring the desired horizontal row of the type plate into printing position, a carriage arm journaled to the driven shaft and adapted to impart movements to the carriage, a clutch mechanism interposed between the carriage arm and the carriage, a rotary stop plate pivoted on the type plate reciprocating lever adapted to limit the movements of the carriage arm, means for moving said rotary stop plate to limit the movement of the carriage arm according to the width of the particular character to be struck, means for bringing the desired character and the impression receiving material into printing engagement, spacing means for automatically moving the impression receiving material between words to justify the line, means for automatically adjusting the spacing means, means for moving the impression receiving material for successive lines of printing and means for returning the impression receiving material to its initial operating position.

17. In a typewriting machine, the combination of a type plate member having a plurality of type characters thereon arranged in rows, the characters in each row being of uniform width, a carriage member for supporting impression receiving material adapted to receive impressions from said type characters, means for selectively positioning the type plate member to bring a desired character into printing position with relation to the impression receiving material, means for bringing said characters and the impression receiving material into printing engagement,

means for moving the carriage member varied distances according to the size of the character to be printed, means for moving the carriage member for successive lines of printing, means for returning the carriage member to its initial operating position, and space controlling mechanism for adjusting the spaces between said words for justifying the line comprising a stop arm pivoted to oscillate in a predetermined path, a pair of actuating arms pivoted to oscillate about the same axis as the stop arm, a chain of intermeshing gears operatively connecting said levers with the stop arm and with each other to effect a differential relation in the movement of said arm, and means for moving said operating arms to various selective positions to move the stop arm to its adjusted position.

18. In a typewriting machine, the combination of a movable carriage, a carriage driving arm, a one-way clutch interposed between said carriage and said carriage driving arm, a movable stop member pivoted to oscillate in a predetermined path and adapted to limit the movement of said carriage driving arm, and means for adjusting the position of said stop member comprising a maximum adjustment arm and a minimum adjustment arm pivoted to oscillate about the same axis as the movable stop member, and a train of intermeshing gears operatively connecting said adjustment arms with each other and with the stop member to effect a differential relation in the movement of said arms and said stop member.

19. In a typewriting machine, the combination of a plurality of type characters, a carriage for supporting material adapted to receive impressions from said type characters, means for selectively bringing a series of desired type characters into printing engagement with said impression receiving material to form words thereon, a carriage driving arm for advancing the carriage, means for operating said driving arm, a one-way clutch operatively connecting said driving arm with said carriage, a pivoted stop arm adapted to limit the movement of said driving arm, a pair of pivoted actuating arms, interconnecting means between said actuating arms and said stop arm, and means for moving said actuating arms to various selective positions to effect a desired positioning of said stop arm.

20. In a typewriting machine, the combination of a plurality of type characters, a carriage for supporting material adapted to receive impressions from said type characters, means for selectively bringing a series of desired type characters into printing engagement with said impression receiving material to form words thereon, a carriage driving arm for advancing the carriage, means for operating said driving arm, a one-way clutch operatively connecting said driving arm and said carriage, a pivoted stop arm adapted to limit the movement of said driving arm, a pair of pivoted actuating arms, interconnecting means between said actuating arms and said stop arm to move the stop arm to a position determined by the selective positioning of the actuating arms.

21. In a typewriting machine, the combination of a plurality of type characters, a carriage for supporting material adapted to receive impressions from said type characters, means for selectively bringing a series of desired type characters into printing engagement with said impression receiving material to form words thereon, a carriage driving arm for advancing the

carriage, means for operating said driving arm, a one-way clutch operatively connecting said driving arm and said carriage, a pivoted stop arm adapted to limit the movement of said driving arm, a pair of pivoted actuating arms, a train of intermeshing gears operatively connecting said actuating arms with the stop arm and with each other to transmit to the stop arm, in varied but predetermined ratios, the independent movements of each of said actuating arms.

22. In a typewriting machine, the combination of a movable type plate member having a plurality of type characters thereon, a carriage member for supporting material adapted to receive impressions from said type characters, lever arms adapted to move said type plate to bring type characters into printing position with respect to the said impression receiving material, and means for moving said lever arms to predetermined positions to present previously selected type characters in printing position, said means comprising a plurality of stop members and mechanism for successively bringing said lever arms into alignment with previously selected stop members.

23. In a typewriting machine, the combination of a movable type plate member having a plurality of type characters thereon, a member for holding the material for receiving impressions from said type characters, lever arms for moving said type plate with relation to the impression receiving material, a plurality of movable stop members adapted to be operated selectively to determine the respective positions of said lever arms to present previously selected type characters in printing position, spring actuated mechanisms for successively bringing said lever arms into alignment with the stop members representing said previously selected type characters, and means for successively bringing said selected type characters into printing engagement with said impression receiving material.

24. In a typewriting machine, the combination of a type plate member having a vertical row of type characters arranged thereon, a carriage member for supporting material adapted to receive impressions from said type characters, means for bringing the impression receiving material and the type plate member into printing engagement, means for moving the type plate to successively place any desired type character in that row in printing position, said means moving the type plate directly by the shortest distance when replacing the type character in printing position by another desired type character, and mechanism for automatically operating the two above mentioned means in properly timed relation to one another.

25. In a typewriting machine, the combination of a type plate member having a horizontal row of type characters arranged thereon, a carriage member for supporting material adapted to receive impressions from said type characters, means for bringing the impression receiving material and the type plate member into printing engagement, means for moving the type plate to successively place any desired type character in that row in printing position, said means moving the type plate directly by the shortest distance when replacing the type character in printing position by another desired type character, and mechanism for automatically operating the two above mentioned means in properly timed relation to one another.

26. In a typewriting machine, the combina-

tion of a type plate supporting shaft, a type plate mounted on said shaft and having a plurality of type characters thereon, a carriage member for supporting material adapted to receive impressions from said type characters, a drive shaft, a pair of type plate positioning members journaled for movement in either direction on said drive shaft and adapted respectively to impart rotational and reciprocal movements to said type plate, and means operated by said drive shaft for successively and selectively positioning the respective positioning members to place a series of predetermined type characters in printing position, the movements of each positioning member being in a single direction for each type positioning operation.

27. In a typewriting machine, the combination of a type plate supporting shaft, a type plate mounted on said shaft and having a plurality of type characters thereon, a carriage member for supporting material adapted to receive impressions from said type characters, a drive shaft, a pair of type plate positioning members journaled for movement in either direction on said drive shaft and adapted respectively to impart rotational and reciprocal movements to said type plate, and mechanism operated by said drive shaft for intermittently engaging the respective positioning members to selectively move the same to present a series of predetermined type characters in printing position, the respective movements of each positioning member being limited to a single direction for each type positioning operation.

28. In a typewriting machine, the combination of a plurality of type characters, a carriage for supporting material adapted to receive impressions from said type characters, means for selectively bringing a series of desired type characters into printing engagement with said impression receiving material to form words thereon, a driving arm for advancing the carriage, means for operating said driving arm, a one-way clutch operatively connecting said driving arm with said carriage, an adjustable stop positioned in the path of a portion of the driving arm for limiting the movement of said driving arm, and means for selectively moving said stop along said path into any required position to limit the movement of the driving arm to provide spaces of substantially equal amplitude between the words for line justification.

29. In a typewriting machine, a typewriting mechanism comprising a type-plate member having a plurality of type characters of various widths arranged in fixed vertical and horizontal rows, a carriage member for supporting impression receiving material adapted to receive impressions from said characters, means for selectively positioning said members in relation to each other for successive impressions of type characters of different widths to form words, and space controlling mechanism adapted to be set before the printing of said words to determine the width of the spaces to justify the lines, said spaces all being of equal amplitude; said typewriting mechanism being in combination with a previously prepared actuating tape having a series of surface irregularities permanently patterned thereon, the first of said series presented for each line being adapted to set the space controlling mechanism for line justification and subsequent surface irregularities being adapted to control the selective positioning means.

45 secured to the shaft 42 and meshing with a gear sector 46 (Fig. 3) on an arm 47 of a bellcrank. The bellcrank 48 is journaled to oscillate about the axis of the continuously driven shaft 5 38, heretofore referred to. The shaft 38 is mounted at 49 to a fixed part of the machine and parallel to the shaft 42. The arm 50 (Fig. 8) of the bellcrank 48 is provided with a depending contact pin 51 which is engaged by the 10 closing movement, hereinafter described, of a pair of clamp jaws, thereby swinging the bellcrank about its axis and imparting an oscillatory movement of predetermined amplitude to the shaft 27 and to the type plate B.

15 However, before describing the mechanism for predetermining the amplitude of movement of the bellcrank 48 and the proportionate oscillating movement to the type plate B, it will be well to describe the mechanism for imparting an axial or reciprocating movement to the type plate B. Returning, therefore, to the sleeve member 39 (Fig. 3) which, as previously noted, is splined to the shaft 42. The lower portion of said sleeve member is formed with gear teeth 25 52 to provide a circular rack 53 adapted to be driven by a pinion gear 54 to raise or lower the sleeve member 39. The said gear is keyed to a stub shaft 55 which is rotatably mounted in supporting brackets 56 and 57. The opposite end of 30 the stub shaft is provided with a bevel gear 58 which meshes with a rack 59 carried on a bellcrank 60. This bellcrank, like the bellcrank 50, is also journaled on the vertical shaft 38. The arm 61 of bellcrank 60 is provided with a projecting contact pin 62 adapted to be engaged by the closing movement of a pair of jaws whose movements are controlled, as hereinafter described, to determine the amplitude of movement 35 of the arm 60 and thereby control the extent of the reciprocating movement of the sleeve member 39 and the type plate B. The movement of the other arm of bellcrank 60 does not affect the movement of the type plate B, and, therefore, may be disregarded for the 40 moment.

45 Having thus far determined the arm 50 of the bellcrank 48 for oscillating the type plate B and the arm 61 of bellcrank 60 for reciprocating the type plate B, the mechanism will next be described for predetermining the movement imparted to the arms 50 and 61 to so position the type plate B that a desired type face is in printing position, i. e., opposite the contact end of the hammer arm 19.

55 The positioning stops

60 This mechanism comprises broadly two sets of stops of fifteen each, one set 63 (Fig. 8) for the oscillating mechanism (bellcrank arm 50) and the other set 64 (Fig. 9) for the reciprocating mechanism (arm 61 of bellcrank 60). The respective stops of set 63 are designated (Fig. 8) by the characters A to N, inclusive, and likewise the respective stops of set 64 are marked (Fig. 65 9) from 1 to 15 inclusive. Each of the stops of the set 63 for the oscillating mechanism represents a particular vertical row of the type plate B, and are so positioned that when the arm 50 of bellcrank 48 is in alignment with the stop 70 representing for example the G row of the type plate B (Fig. 4) the G row of the type plate B is directly opposite the hammer arm 19. In like manner, each of the stops of the set 64 for the reciprocating mechanism represents a particular horizontal row of the type plate B and

75 are so coordinated with the arm 61 of bellcrank 60 that when the arm 61 is in alignment with a particular stop, the horizontal row of the type plate B represented by said stop will be directly opposite the hammer arm 19. For a purpose, 5 hereinafter explained, stops 63 and 64 are so arranged that the vertical axes of respective stops of each set are an equal distance apart on a 45° arc described from the axis of the drive shaft 38. Set 64 is positioned directly above set 10 65 and on a similar 45° arc. As will now be readily seen, any desired character on the type plate B may be brought into printing position by aligning the arm 50 with the stop of the set 15 63 representing the vertical row in which the desired character is located, and, at the same time, aligning the arm 61 with the stop of the set 64, representing the horizontal line in which the desired character is located on type plate B. The mechanism for actuating the stops 63 and 20 64 and means for bringing the respective arms 50, 61 into alignment with the particular stops actuated will now be described in detail.

The stop actuating mechanism

25 Referring now to Figs. 1 and 8, the stops 63, being the vertical row stops, are slidably supported in holes in a block 65 which is fixed by suitable means to the frame of the machine. Block 65 is of substantially less thickness than 30 the length of the stops 63, so that they will protrude from the upper and lower surfaces thereof. The upper ends of all of the stops, except the stop 63', are normally held retracted within the block 65 by means of coil springs 68. 35 The lower end of each stop is seated on one of a set of fifteen stop levers 66 (Fig. 3). The stop levers 66 are fulcrumed at 67 to a fixed part of the machine. Each lever is actuated, by a suitable electro-magnet, to move its particular stop 40 upwardly so that it will protrude above the upper surface of the block 65. The stops 63 and their supporting block 65 are mounted slightly below and beyond the outer end of arm 50 which carries the projecting pin 51.

45 The stops 64, being the horizontal row stops, are somewhat similarly supported in a block 69 adjacent the axial or reciprocal positioning arm 61. The stops 64 are slidably supported in the block 69 and, except for the stop 64', are normally held retracted within the block by means of coil spring 73. The said stop 64', however, normally projects below the block 69. Each one of a set of stop levers 71, seated on a corresponding stop 64, is fulcrumed at 72 to a fixed 55 part of the machine and, like the stop levers 66, is actuated, by means of a suitable electro-magnet, to move its particular stop downwardly so that its lower end will protrude from the lower surface of the block 69. The stops 64 and their supporting block 69 are mounted slightly above and beyond the outer end of arm 61, carrying the projecting pin 62.

60 Before proceeding with the description of the mechanism for actuating the stop levers 66 and 65 the stop levers 71 to move any desired stop out of its normal position, reference will first be made to the operating ribbon H.

65 When a character key is struck on the monotype composing machine, two perforations are 70 ordinarily made on the monotype ribbon; one perforation denoting the horizontal or numbered row of the type-plate B (Fig. 4) in which the corresponding type face is located; the other perforation denoting the vertical or lettered row 75

(Fig. 4) in which the same type face is located. The said two perforations are required, therefore, to determine the exact position on the type plate B to properly locate a desired type face 5 in position for printing.

As the perforated ribbon is fed into the apparatus it passes between contact members and normally holds open the electric circuit through the magnets for operating the levers 66—71. 10 However, when the two perforations above referred to move into register with predetermined contact members, the said contacts come together so as to close two electric circuits. One of these circuits will energize a magnet adapted 15 to actuate the desired vertical positioning stop lever 66 and the other circuit will energize a magnet adapted to actuate the desired horizontal positioning stop lever 71.

Referring to Fig. 1, each of the magnets 74 is 20 mounted on a suitable bracket 75 which is suitably secured to a fixed part of the machine. Adjacent each of the magnets and projecting somewhat thereabove is a push rod or stop lever 25 actuating rod 76 which extends downwardly and into engagement with one of the stop levers 66, 71, as the case may be. Pivoted to the top of each push rod 76 is a magnet armature 77. Each of the armatures 77 is adapted to respond to the energization of its magnet 74 and to 30 thereby actuate its push rod 76 which will rock its stop lever 71 or 66, as the case may be, to, move one of the stops into the path of movement of jaws for operating the levers 50—61.

In the preferred embodiment of the machine 35 the middle or H stop of the group 63 (Fig. 8), designated as 63' and representing the center vertical row on the type plate B, normally protrudes beyond the upper surface of block 65. The lower end of this stop is secured by a suitable 40 socket 78 (Fig. 1) to a stop lever 79 fulcrumed at 67 to a fixed part of the machine. A spring 80 (Fig. 6) tends to hold the stop 63' in its normal position. Lever arm 79 is adapted to be swung by push rod 81, armature 82, and 45 magnet 83, all of which are of like construction as push rods 76, armatures 77, and magnets 74.

In similar manner the middle or #8 stop of the group 64 (Fig. 3), designated by the reference character 64' and representing the center 50 horizontal row on the type plate B, normally protrudes beyond the lower surface of block 69. This stop is actuated by a magnet 84, armature 85, push rod 86 and stop lever 87 in like manner as the other stops of set 64 except that the 55 lever arm 87 to which stop 64' is secured by ball socket 70, is fulcrumed between the push rod 86 and the stop 64' to reverse the movement.

This preferred construction makes it unnecessary to perforate the ribbon when it is desired 60 to indicate the center character of the type plate, said construction also makes it practicable to eliminate one of the perforations when the character desired to be printed is in either of the center rows. The magnets actuating these two 65 stops are wired, as hereinafter described, to be energized simultaneously with the energization of any other magnet.

Mechanism for aligning oscillating and reciprocating arms

70 Journalized on the vertical shaft 38 at a point below the bellcrank 48 is a pair of cooperating clamp jaws 88, 89 (Figs. 7 and 8) which jaws as before noted position the lever 50 relative to 75 a particular stop 63. The outer portion of

clamp jaw 88 is bent upwardly into the same horizontal plane as jaw 89 and both jaw members 88 and 89 are adapted, when in closing engagement, to grip the depending pin 51 of arm 50 and also whatever stop of the set 63 may be 5 projecting above the upper surface of the block 65. Jaws 88, 89 are moved to their closed position by springs 90, 91, and are opened by means of a cam 92, a cam lever 93, and equalizing links 94, 95, 96, the opening movement of said jaws 10 being limited by fixed stops 89a. The cam 92 is keyed at 97 to the vertical shaft 38, and is adapted during the rotation of the shaft to actuate cam lever 93 twice for each revolution of the drive shaft. Preferably, a roller 98 is 15 carried by the lever 93 to bear against the edge of the cam. One end of the cam lever 93 is pivoted at 99 to a fixed part of the machine and the other end is pivotally connected to the center of equalizing link 95. The link member 94 20 is pivoted at one end to the jaw member 88 and at the other end to one end of the equalizing link 95. The link member 96 is likewise pivoted to jaw member 89 and to the opposite end of equalizing link 95. This equalizing or compensating mechanism is necessary from the fact that the position of the clamp jaws 88, 89 when in closing engagement is variable depending upon the particular stop which may protrude 25 into the path of the jaws. 30

A like pair of jaws 100, 101 (Fig. 9) adapted to bring the arm 61 into alignment with any desired stop of the group 64, is operated by a cam 102, cam lever 103, and equalizing links 104, 105, 106 and springs 106a and 106b, stops 101a all 35 of which are of the same construction as the corresponding parts of the jaw members 88, 89 and occupy the same relative positions to the arm 61 and the shaft 38. The outer end of a cam lever 103, however, is pivoted to a fixed sector plate 107, the said sector plate being held against movement by reason of a suitable attachment to the machine frame. 40

It will be seen that with the proper timing, to be hereinafter described, during one-half revolution of the drive shaft 38, the stop actuating mechanisms will move one stop of the set 63 into the path of the clamp jaws 88, 89 and one stop of the set 64 into the path of the jaws 100, 101; the jaws 88, 89, and 100, 101 will close on the respective stops, aligning the respective arms 50 and 61, thereby moving the desired character of type plate B into printing position; and the hammer 19 will be actuated to bring the paper 8, the ribbon 15 and the desired type character into printing engagement. 55

Character space advance

The mechanism now to be described operates 60 to move the carriage A, after a character has been printed, a distance corresponding to the normal width of the next character to be printed. Bearing in mind that the perforated ribbon H (Fig. 5) is fed into the machine in reverse 65 order and consequently the printing is done backward, it will be understood that the next letter to be printed is in effect anticipated and therefore the necessary space can be pre-arranged. 70

The mechanism for advancing the carriage a distance corresponding to the width of the particular character to be struck comprises broadly, the carriage advance clutch mechanism 108 (Fig. 15); a clutch operating arm 109; and 75

30. In a typewriting machine, a typewriting mechanism comprising a type plate member having a plurality of type characters of various widths arranged in fixed vertical and horizontal rows, a carriage member for supporting impression receiving material adapted to receive impressions from said characters, means for selectively positioning said members in relation to each other for successive impressions of type characters of different widths to form a series of words, and space controlling mechanism adapted to be set before the printing of said words to determine the widths of the spaces to justify the lines, said spaces all being of equal amplitude.

5 10 15 20 25 30

5 rows, a carriage member for supporting impression receiving material adapted to receive impressions from said characters, means for selectively positioning said members in relation to each other for successive impressions of type characters of different widths to form a series of words, and space controlling mechanism adapted to be set before the printing of said words to determine the widths of the spaces to justify the lines, said spaces all being of equal amplitude.

10 15 20 25 30

10 characters of different widths to form a series of words, and space controlling mechanism adapted to be set before the printing of said words to determine the widths of the spaces to justify the lines, said spaces all being of equal amplitude.

15 20 25 30

15 tude; in combination with a previously prepared actuating device having a series of surface irregularities patterned thereon, said surface irregularities being adapted to actuate the space control means and the selective positioning means

20 to print a series of justified lines in which the various characters are printed on spaces corresponding to their respective widths.

31. In a typewriting machine, the combination of a type plate member having a plurality of type characters of various widths arranged in fixed vertical and horizontal rows, a carriage member for supporting impression receiving material adapted to receive impressions of said characters, character selecting mechanism for selectively moving the type plate to successively present a series of type characters in printing position with relation to the impression receiving material, said character selecting mechanism controlling the movements of the carriage between each character and the next according to the width of the character next being presented, means for selectively positioning the type plate member and the carriage member in relation to each other for successive impressions of type characters of different widths to form a series of words, and space controlling mechanism adapted to be set before the printing of said words to determine the width of the spaces to justify the lines, said spaces all being of equal amplitude.

35 40 45 50 55 60

32. In a typewriting machine, a typewriting mechanism comprising a type plate member having a plurality of type characters of various widths arranged according to their respective widths in fixed vertical and horizontal rows, a carriage member for supporting impression receiving material adapted to receive impressions from said characters, means for selectively positioning said members in relation to each other for successive impressions of type characters of different widths to form a series of words, a carriage advance mechanism for exerting exclusive control of the advance movements of the carriage, and space controlling mechanism adapted to be set before the printing of said words to limit the movement of the carriage advance mechanism to provide spaces between words of proper amplitude to justify the lines, said spaces all being of equal amplitude.

33. In a typewriting machine, the combination of a type plate member having a plurality of type characters of various widths arranged in fixed vertical and horizontal rows, a carriage member for supporting impression receiving material to receive impressions from said characters, means comprising a type selecting mechanism, carriage advance mechanism and printing mechanism, for selectively positioning said members in relation to each other for successive impressions of type characters of different widths to form a series of words, and space controlling

mechanism comprising a stop adapted to be set in fixed and immovable position before the printing of said words to be engaged by the carriage advance mechanism to limit the normal movement thereof to determine the width of the 5 spaces to justify the line, said spaces all being of equal amplitude.

34. In a typewriting machine, the combination of a type plate member having a plurality of type characters of various widths arranged in fixed vertical and horizontal rows, a carriage member for supporting impression receiving material adapted to receive impressions from said characters, character selecting means for selectively positioning said type plate to bring a succession of desired type characters into printing position with relation to the impression receiving material, printing means for successively bringing the selected type characters into printing engagement with the impression receiving material, means for imparting movement of varied amplitude to the carriage according to the width of the character to be printed, carriage advance means to advance the carriage to provide spaces between words, space controlling mechanism adapted to be set before the printing of said words to determine the width of the spaces to justify the lines, said spaces all being of equal amplitude, and mechanism, comprising a portion of said character selecting means, for setting 30 the space controlling mechanism for the purpose aforesaid.

35. In a typewriting machine, the combination of a type member having a plurality of type characters of various widths, a carriage member for supporting material adapted to receive impressions from said type characters, means for selectively positioning said members in relation to each other for successive impressions of type characters of different widths to form a series of words, a carriage advance mechanism, a space control mechanism independent of the carriage and comprising an adjustable stop for limiting the normal movement of the carriage advance mechanism, and means comprising a 40 45 gear for moving the stop to modify the movement of the carriage advance mechanism to provide spaces of substantially equal amplitude between the words for line justification.

36. In a typewriting machine, the combination of a type member having a plurality of type characters of various widths, a carriage member for supporting material adapted to receive impressions from said type characters, means for selectively positioning said members in relation to each other for successive impressions of type characters of different widths to form a series of words, a carriage advance mechanism for exerting exclusive control of the advance movements of the carriage, and an adjustable stop for 50 55 60 65 limiting the normal movement of the carriage advance mechanism to provide spaces of equal amplitude for line justification, said adjustable stop being gear operated.

37. In a typewriting machine, the combination of a type member having a plurality of type characters of various widths, a carriage member for supporting material adapted to receive impressions from said type characters, means for selectively positioning said members in relation to each other for successive impressions of type characters of different widths to form a series of words, a carriage advance mechanism, and an adjustable stop member adapted to be engaged by the carriage advance mecha- 70 75

- nism for limiting the normal movement of the carriage advance mechanism, said stop member remaining fixed in its adjusted position throughout the printing of a line.
5. 38. In a typewriting machine, a type plate member having a plurality of type characters of various widths arranged in fixed vertical and horizontal rows, a carriage member for supporting impression receiving material adapted to receive impressions from said characters, means for selectively positioning said members in relation to each other for successive impressions of type characters of different widths to form a series of words, space controlling mechanism adapted to be set before the printing of the words to determine the width of the space to justify the line, said spaces all being of equal amplitude, means for moving the space controlling mechanism to its adjusted position, and an actuating tape for the above mechanism having a series of perforations patterned thereon, the first of said series presented for each line being adapted to set the space controlling mechanism for line justification, and subsequent perforations being adapted to control the selective positioning means.
39. In a typewriting machine, a type plate member having a plurality of type characters of various widths arranged in fixed vertical and horizontal rows, an impression receiving member adapted to receive impressions from said characters, means for selectively positioning said members in relation to each other for successive impressions of type characters of different widths to form a series of words, space controlling mechanism adapted to be set before the printing of the words to determine the width of the spaces to justify the line, said spaces all being of equal amplitude, means for moving the space controlling mechanism to its adjusted position, means for releasably holding the space controlling mechanism in its set position; in combination with a previously prepared actuating tape having a series of indicating perforations patterned thereon, said tape being adapted to actuate the space controlling means and the selective positioning means to print a series of justified lines in which the various characters are printed on spaces corresponding to their respective widths.
40. In a typewriting machine, a typewriting mechanism comprising a type plate member having a plurality of type characters of various widths arranged in fixed vertical and horizontal rows, a carriage member for supporting impression receiving material adapted to receive impressions from said characters, means for selectively positioning said members in relation to each other for successive impressions of type characters, means for bringing each type character as selected into printing engagement with the impression receiving material, means for moving the carriage member from right to left

between each successive impression to form a series of words on said impression receiving material, and space controlling mechanism adapted to be set before the printing of said words to determine the width of the spaces to justify the lines, said spaces all being of equal amplitude; in combination with an actuating device adapted to operate the selective positioning means to present successive type characters for printing words in reverse order of their spelling.

41. In a typewriting machine, the combination of a type plate member having a plurality of type characters of various widths arranged in fixed vertical and horizontal rows, a carriage member adapted to support impression receiving material, means for selectively positioning said type plate member to bring a series of type characters into printing position with respect to said impression receiving material, means operatively connecting the carriage member with the selective positioning means to impart movements of varied amplitude to the carriage in relation to the selective positioning of the type plate, and space controlling mechanism adapted to be set before the printing of said words to determine the width of the spaces to justify the line, said spaces all being of equal amplitude.

42. In a typewriting machine, a typewriting mechanism comprising a type plate member having a plurality of type characters thereon, a carriage member for supporting impression receiving material adapted to receive impressions from said type characters, means for selectively positioning the type plate member in relation to the carriage member to bring a series of desired type characters into printing position, means for successively bringing the selected type characters into printing engagement with the impression receiving material, carriage advance mechanism for moving the carriage between each successive printing engagement to form a series of words on the impression receiving material, said carriage advance mechanism exerting exclusive control over the advance movements of the carriage, space control mechanism comprising a stop adapted to be adjustably positioned in the path of normal movement of the carriage advance mechanism to limit the effective movements thereof to provide carriage movements of proper amplitude for line justification, the spaces between words all being of equal amplitude, and an actuating mechanism comprising a tape having thereon a series of previously prepared surface irregularities in code arrangements adapted to automatically operate the selective positioning means, the printing means, the carriage advance mechanism and the space control mechanism to print from right to left within a predetermined space on the impression receiving material a justified line of words.

WILLIAM OSCAR BELL.
